UNITED STATES PATENT OFFICE

HERBERT M. FRIENDLY, OF PORTLAND, OREGON; MILTON S. FRIENDLY AND CENTRAL TRUST COMPANY OF ILLINOIS, EXECUTORS OF SAID HERBERT M. FRIENDLY, DECEASED

TELEPHONE SYSTEM

Application filed June 29, 1921, Serial No. 481,259. Renewed March 9, 1927.

The present invention has for its broad objects the improvement of telephone systems in general, and more particularly automatic and semi-automatic systems, looking toward 55 the affording of operative conveniences to users and benefits to the operating concern that have been heretofore unknown.

The invention in the specific form chosen for the illustration herein, contemplates a so-called two-wire common battery automatic telephone system as has been widely used, the present invention necessitating novel departures from equipments heretofore known, in attaining the new objects, while retaining 60 certain operative functions which are known.

The exampled form of the present invention, chosen to illustrate it, contemplates its adaptation to a comprehensive five-digit automatic telephone exchange system consisting 65 of main branch offices and a sub-office of one of the main-branch offices. It has for its objects the following and other novel objects.

a. To provide a novel dual-functioning switch in a sub-office primarily seizable by a subscriber's terminating line-switch (also termed a pre-selector), which dual-functioning switch will operate in an idle manner so far as its cooperative functioning by way of extending the call in the direction of the 70 called subscriber is concerned, until the first two digits of the called number which incidentally index the sub-office and the sub-office division, have been sent, whereupon the said switch seized by the primary line switch will 75 be automatically converted into a switch having the functions of a third selector.

a2. Incidental to the second digit being called, whereupon the switch is converted into a selector, as set forth, a supplemental condition is set up which bars the switch from seizing connectors in a specific thousands group and opens the way for selecting connectors in an alternative thousands group. That is to say, the switch functioning as a selector has access to ten hundreds groups of connectors in each of two thousands groups, and further that the second digit sent will not only index, but will set the switch for selecting only in the numerically corresponding thousands group of con-

nectors. The switch, due to its condition set-up incident to receiving the second digit series, though its wipers have been restored to normal position, now involves a pre-selection of one of two thousands groups, so 55 the next operation of the switch responsive to the third digit series will be to select the directed hundred in the said pre-selected thousands group. Upon the fourth and fifth digits being set the selected connector will 60 function in the well known manner to effect the completion of the connection to the called subscriber.

b. Permanently related to the dual-functioning switch is a novel duplex lineswitch 65 which functions in a secondary manner incident to the seizure of the former, whereupon it will automatically seize an idle trunk extending through a reciprocal-functioning switch to an incoming first selector in the main-branch office to which the sub-office belongs. So that upon the calling subscriber initiating the call from his station connected subordinate to the sub-office, his terminating lineswitch (primary) will automatically 70 function and seize an idle dual-functioning switch and the seized dual-functioning switch will consequently capacitate its permanently related duplex lineswitch (secondary) so it will automatically function to seize 75 an idle outgoing trunk from the sub-office to its comprising main-branch office, where it terminates in an incoming first selector, the latter being now in readiness to receive the first series of impulses constituting the first 80 digit of the called number. The dual-functioning switch is also susceptible to the said series of impulses constituting the first digit. That is to say, the dual-functioning switch located in the sub-office and the first selector 85 in the main-branch office terminating the automatically inter-linked trunked connection from the subscriber's station will coincidently operate under directive control of the calling device at the calling subscriber's 90 station in step-by-step manner.

b2. The said incoming first selector in the main-branch office has the well known cooperative relation with the second selectors 95 in the main-branch office, so that by the call- 100

ing subscriber calling digits comprising a telephone number reached through its main-branch office, the call will be advanced in the direction of the called subscriber as in the 5 well known condition wherein a subscriber whose line leads directly to a lineswitch in the main-branch office initiates a call and automatically attains connection with a local first selector. However, under the condition 10 of forwarding the call from the incoming first selector controlled by the sub-office calling subscriber, the dual-functioning switch in the sub-office will rotate on its normal level (not stepping-up its shaft), and then release 15 to normal position at the termination of the first digit series, provided the first digit is pertinent to the sub-office. It remains at rest in its rotated-in position, incapacitated 20 against further operative movement or affecting condition of the connection being established, if the first digit sent is not pertinent to the sub-office, and there remains until the calling subscriber replaces his receiver. 25 It is to be borne in mind that upon the calling subscriber sending the second digit, the second selector in the main-branch office will function in a normal manner in extending the connection in the direction of the third selectors, and attains connection with a third 30 selector level corresponding to a thousands group indexed by the second digit sent. If the dual-functioning switch does not restore to normal position following the sending of the second digit and, therefore, remains at 35 rest where stepped-in, the succeeding digits will progress the call in the direction of the called subscriber by way of the main-branch office because the call is not destined to a subscriber's line in the sub-office.

40 33. Assuming that the first digit sent is pertinent to the sub-office and, therefore, the dual-functioning switch will rotate-in and then release to normal resultant to the first digit being sent, and that the second digit 45 of the called number is now sent and which is also pertinent to the sub-office, the dual-functioning switch which operated in the manner as before will again release to normal position resultant to the second digit being sent. Incidental to the second releasing 50 of the dual-functioning switch to normal position, it automatically prepares its circuits (which are partially prepared incident to the said first release) to control its 55 moving elements as a third selector, and it also causes the trunk seized through the duplex lineswitch to be released and be again seizable from either the sub-office end or the main-branch office end thereof.

60 Upon the calling subscriber sending the third digit of the called number, which will be pertinent to a hundreds group of the thousands group in the sub-office indexed by the second digit, the dual-functioning 65 switch (functioning as a selector) will step

its wipers up into alignment with the bank level corresponding to the two groups of connectors (wherein one of the groups has access to the called line), where it will automatically rotate-in and seize an idle one of these specific hundreds connectors in the thousands group determined, incidentally by the second digit sent. Upon the calling subscriber annexing the last two digits of the called number, the seized connector of the 70 hundreds group indexed by the third digit will function in the well known manner and connect to and signal upon the called line. Upon the called subscriber responding, the telephone circuit from the calling to the 75 called subscriber will be established.

c. To provide a set or pair of novel lineswitches, operated as a unit, hereinbefore referred to as a duplex lineswitch, wherein an element C thereof will at all times start 80 automatically functioning where necessary to be prepared to seize an idle trunk without first rotating. That is to say, to always rest its wipers on the bank contacts of an idle trunk and to automatically move off and seek 85 an idle set of trunk bank contacts upon which to rest its wipers should the trunk become busy by reason of it being seized from some other point. An element B of the duplex lineswitch is designed to operate preferentially over the said element C when the leading-conductors are seized. That is to say, the element B will be the only element that 90 will seize the set of bank contacts of a trunk its wipers may be resting upon, if the trunk 95 is idle, or that will automatically start its rotation seeking an idle trunk to seize, if the duplex lineswitch is seized. However, a 100 function of the duplex lineswitch is that, after the B element thereof has started its 105 automatic rotation hunting for an idle trunk (if its wipers were not resting upon an idle trunk) and has passed over a pre-determined number of trunks as busy, the C element of the duplex lineswitch will become operative, 110 that is it will either seize the idle trunk the bank contacts of which its wipers are resting upon, or in case the trunk that its wipers were resting upon the bank contacts of which became busy before it was operatively introduced, upon the B element having passed over the pre-determined number of busy trunks, will also start a hunting operation 115 so that under this condition both elements of the duplex lineswitch will seek or hunt for 120 an idle trunk. The first element (B or C) to encounter an idle trunk will seize it and incidentally incapacitate its companion element. In instances in commercial operation the trunks accessible to the C element 125 would be over-flow trunks, not seizable to the B elements of duplex lineswitches, but comprise an auxiliary or reserve group provided so as to insure they would not be used unless there was a shortage of idle trunks in the 130

general group as indicated by the fact that the B element has rotated over the pre-determined number of trunks without finding an idle one.

5 c2. A function of the duplex lineswitch is that of rendering its leading-in terminals non-seizable by applying a false busy thereto during the period the C element may be automatically rotating, because the trunk 10 that it may be normally resting upon has become busy, by reason of a switch commonly accessible to it (from either end thereof) having seized it.

15 d. A further function of the duplex lineswitch is that if all the trunks accessible to both elements thereof in common with other lineswitches become busy a condition is set-up whereby, when the C element (or elements 20 of a plurality of duplex lineswitches) start rotating automatically from the last idle trunk contacts, because of the trunk becoming busy, or that the B element is in the process of hunting wherein all trunks are busy, the rotating test wiper will encounter a bank contact that, due to the set-up condition, will cause the duplex lineswitch element concerned to seize and, therefore, stop rotating, and apply a specific tone indexing the condition to the calling subscriber.

25 e. To provide a novel selector (herein termed a reciprocal-functioning switch) in the sub-office terminating an inter-office trunk for forwarding incoming traffic through its wipers that also comprehends the 30 use wherein it will reciprocally function as a trunk repeater when its related trunk is seized as an outgoing trunk to the main-branch office.

35 e2. A further function of the selector referred to in the foregoing paragraph (which may also be termed a second-third selector of the sub-office) is that it will select in one of two alternative thousand trunk groups leading to hundreds groups of connectors thereof, depending upon the numerical value of the third digit called in extending a connection from a calling subscriber's telephone in a main-branch office to a subscriber's telephone in the sub-office.

40 f. To provide a novel means in a lineswitch whereby if the lineswitch continues to automatically rotate over busy trunks and that none accessible to it are found idle, a distinctive tone will be applied to the leading-55 in line, audible to that calling subscriber, apprising him of the condition so that he will refrain from attempting to effect the calling further, knowing that there are no available trunks accessible to the lineswitch and will, therefore, replace his receiver and cause the lineswitch to stop hunting. Heretofore, under the stated condition, the lineswitches would frequently rotate for a prolonged period while a calling subscriber 60 either held the line or proceeded with the call

operations which, of course, would be ineffectual.

In the accompanying drawings:

Fig. 1 shows a general layout of a telephone exchange system as contemplated under the present invention. The portion of the diagram within the left hand dotted square is to be understood as belonging to the sub-office. The portion within the upper righthand dotted square is to be understood 70 as belonging to the main-branch office to the sub-office and which will be referred to as the "2" main-branch office. The portion within the lower righthand dotted square is to be understood 75 as belonging to a main-branch office of the system located contiguous to the "2" office, and which will be hereinafter referred to as the "3" main-branch office, and that the two said main-branch office are connected for inter-switching between all the 80 subscribers thereof under directive control of the subscribers of the entire exchange.

Fig. 2 shows the assembly of the various sheets of drawings forming the system indicated in Fig. 1.

90 Fig. 3 shows a subscriber's telephone T2 leading into a lineswitch A of well known type, located in the sub-office.

Fig. 4 shows a novel pair of inter-linked or companion lineswitch elements B and C, 95 hereinafter referred to as a duplex line switch.

Fig. 5 shows a novel dual-functioning switch D located in the sub-office which will function to divert a call in the direction of 100 the called subscriber in the sub-office.

Fig. 6 shows a novel combination incoming first selector and outgoing trunk repeater E hereinafter referred to as a reciprocal-functioning switch, and is located in the sub-office.

105 Fig. 7 shows a subscriber's telephone T7 accessible to a connector G, and a subscriber's telephone T7' accessible to connector F. It also shows said connector F as having access 110 to subscriber's telephone T2; all in relation to the sub-office of the "2" main-branch office.

Fig. 8 shows armatures on four relays of four respective switches of a group that are 115 companion to and similar to E, and are located in the sub-office of the "2" main-branch office.

Fig. 9 shows a novel in-coming first selector H in the "2" main-branch office, terminating a trunk from the sub-office. The selector H from the right of the armatures of the left relay is the same as selectors which are well-known.

120 Fig. 10 shows a novel outgoing trunk repeater interlinked with selector H and located in the "2" main-branch office and the trunk extending therefrom to the switch E in the sub-office.

125 Fig. 11 shows a local second selector J co-operating with incoming first selector H, a 130

third selector K cooperating with a second selector J and a connector L cooperating with a third selector K, a subscriber's telephone T11 in the "2" main-branch office accessible to the connector L, and a novel lineswitch M associated with the line leading to the said telephone T11, together with a first selector O accessible to the lineswitch M, a local second selector N, accessible to first selector O and a trunk extending from two of the levels of second selector N to the trunk leading to E by way of repeater I.

Fig. 12 shows a subscriber's telephone T12 in the "3" main-branch office leading into a lineswitch R of well known type. The lineswitch R has access to first selector Q, and first selector Q has access to second selector P. The subscriber's telephone T12 reached through the "3" main-branch office is accessible to incoming first selector H in the "2" main-branch office by way of second selector S, third selector T and connector U.

By way of further explanation, selectors, regardless of their denomination, O, N, J, K, Q, P, S, S' and T may be assumed similar in detail to the portion of selector H in Fig. 9 from the right of the left relay thereof. Also, connectors G, L and U may be assumed similar in detail to connector F in Fig. 7, 30 which latter is a well known type of connector.

Referring to certain of the figures:

The subscriber's telephones T2, T7, T7', T11 and T12 are of the usual series type of automatic telephone having a calling device of the general class as shown in British patent to Dicker, No. 29,654 of 1910.

The lineswitches A and R are of the general class as shown in U. S. patent to Lamb, No. 1,193,160 granted Aug. 1, 1916, and are well known. The lineswitch M belongs to the same class as lineswitches A and R with a novel modification thereto to operate in accordance with, and to embody the present invention.

The first selectors H, O, and Q; the second selectors N, P, S and S' and the third selectors T and K are all of the general class as shown in U. S. patent to Keith and Erickson No. 815,321 granted March 13, 1906, of course, modified in mechanical and circuit details to operate on the well known so-called two-wire principle. It is to be understood that a selector, such as E in U. S. patent No. 13,901 reissued to Frank Newforth April 13, 1915, may be substituted for said H (from the right of the armatures of the left relay thereof), O, Q, N, P, S, S', J, T and K throughout the description and for the purposes contemplated under the present invention.

The connectors F, G, L and U are of the general class as shown in U. S. patent to Keith and Erickson No. 815,176, granted March 13, 1906, of course, modified in me-

chanical and circuit details to operate on the well known so-called two-wire principle. It is to be understood that a connector, such as H, in U. S. patent No. 13,901 reissued to Frank Newforth April 13, 1915, may be substituted for said F, G, L and U throughout the description and for the purposes contemplated under the present invention. 70

The duplex lineswitch, made up of the companion elements C and B, the said elements are each of the same general class as lineswitch A, modified of course, to operate in accordance with, and to embody the present invention. 75

The dual-functioning switch D and the reciprocal-functioning switch E are of the same general class as selector H (not considering the relay on the extreme left thereof added in embodying the present invention). The switches D and E are, of course, modified in mechanical and electrical details from the referred to switch H to operate in accordance with and to embody the present invention. 80

It, of course, is understood that in applying the present invention to a commercial system the various elements shown as cooperating with bank contact sets would be installed in plurality depending upon the capacity of the system. Also, that more than one switch would have access to the same lines and trunks through companion bank contacts that are in corresponding multiple relation with the companion bank contacts of other switches. In order not to unduly involve the drawings and descriptions the said multiple connections have not been completely detailed, though they are indicated in some instances by extended lines. For example, 90

there would be a plurality of subscriber's lines, such as is shown leading from T2, terminating in the lineswitch A. Then, a group of lineswitches, such as A, would have common access to a plurality of trunks, each leading to a dual-functioning switch D and its companion secondary duplex lineswitch shown in Fig. 4 as elements B and C. A group of duplex lineswitches (such as companion elements B and C), would have common access to a plurality of trunks each leading to a reciprocal-functioning switch as E and to an incoming first selector in the "2" main-branch office. It will be borne in mind in this connection that the companion duplex lineswitch elements B and C may each have access to individual groups of reciprocal-functioning switches such as E and trunks leading to incoming first selectors therefrom respectively as stated, or that both said elements B and C may have access to a single said group commonly, as is shown in the drawings. 100

To simplify the drawings and descriptions, battery and ground are shown as independent sources throughout, wherever applied, 115 120 125 130

but it is to be understood that the system is of the common battery type. In the descriptions, when a circuit is traced to a winding, the opposite terminal of which is shown applied to grounded battery or to ground, the described circuit is to be considered as traced to ground through the winding to battery, or direct to ground as indicated.

The performance of the equipment will be detailed under different assumed operative conditions, bearing in mind the equipment elements may be further variously organized in the assembly of a system.

Referring to the accompanying drawings:

Assuming a call is made from telephone T2 to telephone T7, the respective calling numbers of which are "22211" and "21211".

Upon the calling subscriber at telephone T2 removing the receiver from the switch-hook to initiate the call, a circuit will be established from the winding of slow-releasing relay 301, armature 302, line conductor 303, telephone T2, line conductor 304, armature 305, to the grounded resting contact thereof, relay 301 actuating. It will be assumed that the wipers 306 to 308 (inclusive) are resting on the bank contacts 309 to 311 respectively, of an idle trunk and that, therefore, the bank contact 309 does not constitute ground potential, as will appear presently. Upon relay 301 actuating, a circuit will be established from winding of motor magnet M3, armature 312, conductor 313, winding of cut-off relay 314, conductor 315 to grounded armature 316. Relay 314 will actuate over this energized circuit but the current will not be of sufficient strength to operatively energize motor-magnet M3 because of the inclusion of the winding of relay 314. Upon the actuation of relay 314, ground from armature 316, conductor 315, contact 317 will be applied, through armature 318 to private wiper 306, bank contact 309, conductor 319 to armature 501 in switch D. A circuit can also be traced from upper winding of relay 502 of switch D, armature 503, conductor 504, bank contact 310, wiper 307, armature 302 over the described path, including telephone T2, conductor 304, armature 305, wiper 308, bank contact 311, conductor 320, armature 505, to lower winding of relay 502, relay 502 actuating. A circuit can now be traced from grounded armature 506, to the winding of slow-releasing relay 507, relay 507 actuating. Armature 501 is now in engagement with grounded contact 508 and contact 509, thus armature 501 has supplemental ground applied to it before relay 301 retracts its period after the attraction of armatures 302 and 318, so that there is no lapse of ground potential on conductor 319 nor conductor 315, relay 314 being now maintained from ground received over conductor 319 from grounded contact 508.

Ground from contact 508 is applied through armature 501, conductor 319, arma-

ture 512, conductor 513, to the winding of relay 401, the latter relay actuating. Slow-releasing relay 402 will coincidently actuate, as will appear presently. It will be assumed that wipers 403 to 406 of element B are resting on the bank contacts 407 to 410, respectively, of an idle trunk and that, therefore, the bank contact 407 does not constitute ground potential, as will appear presently.

An operative circuit can be traced from grounded conductor 319, conductor 418, armature 411, armature 412, armature 413 to the winding of relay 402. Upon relay 402 actuating, a circuit will be established from the winding of motor magnet M4, armature 414, conductor 413 winding of relay 416, armature 417, to conductor 418 which leads to grounded conductor 319. Relay 416 will

actuate over this energized circuit, but the current will not be of sufficient strength to operatively energize motor magnet M4 because of the inclusion of the winding of relay 416. A circuit can now be traced from grounded conductor 418, armature 420, armature 422, wiper 404, bank contact 408,

conductor 423, conductor 424, to the winding of slow-releasing relay 601, the latter relay actuating. A circuit can also be traced from grounded conductor 418, through armature 420, wiper 403, bank contact 407, conductor 426, conductor 427, to armature 602.

A circuit can also be traced from upper winding of relay 603, make-before-break spring 604, upper winding of relay 605, armature 606, armature 607, conductor 608, make-before-break spring 609, conductor 428, conductor 429, bank contact 409, wiper 405, armature 430, conductor 431, conductor 504, bank contact 310, wiper 307 over the de-

scribed path including telephone T2, wiper 308, bank contact 311, conductor 320, conductor 322, contact 433, wiper 406, bank contact 410, conductor 434, conductor 435, make-before-break spring 610, conductor 612, armature 613, armature 614, lower winding of relay 605, made-before-break spring 615 to lower winding of relay 603, relay 605 actuating. The windings of relay 603 are so disposed that the current traced through them neutralize each other, and therefore, no trac-

tive effort is exerted upon its armatures. The object of relay 603 will appear presently.

Relay 605, being now actuated, a circuit can be traced from its grounded armature 616 to the winding of slow-releasing relay 617, causing it to actuate. A supplemental ground is applied to conductor 418 from contact 618, armature 602 conductor 427, conductor 426, bank contact 407, wiper 403, armature 420,

to conductor 418. This supplemental ground will prevent a lapse of ground potential occurring to conductor 319 when armature 501 retracts, as will appear presently. So relay 416 is maintained actuated, dependent on armature 602. Also that the traced ground

70

75

95

100

105

110

115

120

125

130

path from wiper 404 to conductor 418 is dependent upon the attracted condition of armature 602. At this juncture, relays 314, 502, 507, 401, 416, 601, 605 and 617 are actuated.

It was hereinbefore described that relay 502 was maintained actuated over a circuit path including conductor 504, telephone T2 and conductor 320. It is, therefore, manifest 10 that both relays 605 and 502 are maintained attracted directly dependent upon the circuit being maintained through the telephone T2.

A circuit can now be traced from lower winding of relay 801, armature 802, armature 15 804, conductor 805, armature 620, conductor 621, armature 622, outside winding of electro-polarized relay 624, conductor 626, armature 627, conductor 628, conductor 629, armature 806, armature 808, upper winding of relay 801, relay 801 actuating. A circuit can 20 now be traced from grounded armature 809, to the winding of slow-releasing relay 810, relay 810 actuating.

Before detailing the assumed call from calling telephone T2 to called telephone T7 attention is directed to the fact that dual-functioning switch D (and companion switches of its group), and reciprocal functioning switch E (and companion switches of its group), have 25 common access to two one-thousand groups of connectors. The wipers of said D are designed to co-operate with eleven levels of bank contacts. The first or lower-most level aligns with the normal position of the wipers 30 and has a novel purpose, as will appear. The ten levels of bank contacts above the said lower-most level are attained by the wipers stepping a corresponding number of vertical steps into alignment therewith, and then 35 automatically rotating-in until a set of bank contacts of an idle trunk is engaged by the set of wipers, when they will be seized. There will usually be ten sets of bank contacts in each level. It follows that since D is the first 40 numerical switch relating to the sub-office, that the position of the levels thereof index the hundred group of connectors to which they lead. That is to say, there will be as many hundreds groups of connectors accessible (being ten one-hundred groups, numbering from one to naught) as there are levels above the normal position of the wipers. However, a novel provision in the reciprocal-functioning switch E enables alternative corresponding hundred groups in two one-thousand groups to be automatically selected through its ten levels, depending upon a set-up condition introduced incidental to seizing the said E through the dual-functioning repeater I, as will appear presently. Suffice it to say, at this time, that the switch D has direct access to two one-thousand connector groups, and therefore, to the two thousand subscriber's lines.

60 the switch D functioning as a selector has direct access to two one-thousand connector groups, and therefore, to two thousand subscribers' lines. It will also appear presently, that these two thousand subscribers' lines 65 have numbers belonging to the "2" main-

branch office, but which, of course, are segregated into the sub-office. It will appear presently that these two thousands are the "1" and "2" thousands of the "2" main-branch office. The telephone T2, as indexed by its telephone number "22211", belongs to the "2" thousand of the "2" main-branch office, or in other words, it belongs to the "22" thousand of the exchange system, and that calling "22" 70 (as the first and second digits of a telephone number) from any subscriber's telephone in the said sub-office of the exchange system will cause the extension of this calling subscriber's line to be reverted to the sub-exchange of the "2" main-branch office containing the said two one-thousand groups of subscribers' 75 lines, and that the switch D then terminating the connection from the calling subscriber's telephone in the sub-office has a set-up condition adapting it to select numbers in the "22" thousand group, barred against selecting numbers in the "21" thousand group thereof.

Attention is also directed to the fact that the wipers of the reciprocal-functioning switch E (and companion switches of its group), is designed to co-operate with ten levels of bank contacts. The said ten levels are attained by the wipers stepping a corresponding number of vertical steps into alignment therewith, and then automatically rotating-in until a set of bank contacts of an idle trunk is engaged by the set of wipers, when they will be seized. There will usually be ten sets of bank contacts in each level. It follows, that since E is the first numerical switch relating to incoming calls to the sub-office, that the position of the levels thereof index the hundred group of connectors to which they lead. That is to say, there will be as many hundreds groups of connectors accessible (being ten one-hundred groups, numbering from one to naught) as there are levels above the normal position of the wipers. However, a novel provision in the reciprocal-functioning switch E enables alternative corresponding hundred groups in two one-thousand groups to be automatically selected through its ten levels, depending upon a set-up condition introduced incidental to seizing the said E through the dual-functioning repeater I, as will appear presently. Suffice it to say, at this time, that the switch D has direct access to two one-thousand connector groups, and therefore, to the two thousand subscriber's lines.

In order not to unduly involve the drawings, a single level, such as lead to connectors, is shown as cooperating with each said D and E respectively. This is the second level, reached and rotated-in upon automatically 110 consequent to the wipers of said D and E respectively being stepped into alignment therewith. The telephonic and private bank contacts of the corresponding levels of the said D and E (and their respective companion 115

120

125

130

switches) are in multiple relation. Bearing in mind that in commercial installations there would ordinarily be ten sets of bank contacts to the level, only the first and third sets of line and private bank contacts of the said second level with respect to the bank contacts of switches D and E are shown as connected in multiple relation, respectively. It will appear presently that the said first sets of multiplied common bank contacts lead to a connector F, and that the said third sets of multiplied common bank contacts lead to connector G. It will also appear presently that the said connector F belongs to the "22" thousand group in the sub-office and that the said connector G belongs to the "21" thousand group in the sub-office. It will further appear presently that which connector F or G is seized, by either said D or E, will depend upon the numerical value of the digit sent next preceding the one sent to complete the connection to the connector seized.

Referring again to the bank contact sets cooperative with the dual functioning switch D and the reciprocal-functioning switch E, it will be noted that the second set of blank contacts respectively are similarly related to the respective switches as is the first set, and therefore, adapted to be terminals of a connector of the same group as contains connector F wherein connector F is the first choice. In a like manner the fourth set of bank contacts respectively are similarly related to the respective switches as is the third set, and, therefore, adapted to be terminals of a connector of the same group as contains connector G wherein connector G is the first choice. Bearing in mind that the levels of bank contacts of D and E would ordinarily have ten or more rotary positions and bank terminals corresponding therewith, it will be manifest that the groups containing connectors F and G may be enlarged so that they will contain five or more connectors each, though the respective groups do not necessarily have to contain an equal number of connectors. The number of connectors in each group would be governed by the traffic requirements. It is manifest then also, that the first five bank contact sets may lead to a group of connectors containing connector G, for example. It will appear that the exampled disposition of the bank contacts last set forth can be modified widely, for example, the first and alternate bank contact sets may lead to connectors of a group containing connector F and the second and alternate bank contact sets may lead to connectors of a group containing connector G.

Returning now to the condition automatically set up consequent to the calling subscriber at telephone T2 removing the receiver. In view of the foregoing description a telephonic circuit has been extended from telephone T2 to armatures 804 and 806 and

to armatures 503 and 505. Relays 314, 502, 507, 401, 416, 601, 605, 617, 801 and 810 are now actuated. Due to conductor 319 being grounded, the trunk seized by lineswitch A will be guarded against intrusion by other lineswitches of the group containing said A. Due to conductor 426 being grounded the trunk leading to switch E seized by duplex lineswitch element B will be guarded against intrusion by other duplex lineswitch elements of the group containing the switch comprised of elements B and C. Due to conductor 315 being grounded, the line leading to telephone T2 will be guarded against seizure by connector F and other connectors of the group containing connector F. Relay 810 being actuated, a circuit can be traced from its grounded contacts 812, conductor 813 to the first bank of contacts 16 and 17 of the first and second levels of second selector N and over conductor 18 to the first bank contacts 19 and 20 of the first and second level of second selector P. Contacts 16, 17, 19, and 20 are private bank contacts of the "2" main-branch office end of the trunk out-going from reciprocal-functioning switch E, so that the said trunk is guarded against intrusion from the "2" main-branch office end consequent to the trunk being seized by the automatic operations initiated by the calling subscriber at telephone T2 removing the receiver.

Upon the calling subscriber manipulating the calling device 322 in accordance with the first digit "2" of the called number, causing two open impulses to the traced path including telephone T2, relays 605, 801, and 502 will de-actuate and re-actuate two times responsive thereto. Referring first to switch D, when grounded armature 506 retracts, a circuit can be traced from said armature, armature 515, armature 516, winding of slow-releasing relay 517, armature 518, conductor 520 to the winding of the rotary magnet R5, causing the said rotary magnet to operate and advance wipers 521 to 524 two rotary positions so that wiper 522 will stop, resting upon bank contact 525. The bank contacts on this level (bearing in mind that the shaft has not been stepped vertically), engageable to wipers 521, 523 and 524 respectively, are unconnected and, therefore, have no operative purpose. Relay 517 is caused to actuate consequent to the circuit including its winding being closed, and upon its de-actuation its period after the last closed impulse, a circuit will be established from grounded contact 508, armature 501, contact 509, conductor 510, armature 526, upper winding of relay 527, conductor 528, armature 529, conductor 530, wiper 522, bank contact 525, conductor 531, make-before-break spring 532 to upper winding of relay 533, relays 533 and 527 actuating. A locking circuit for relay 527 can be traced from its lower winding, armature 534, conductor 535, 130

armature 536, conductor 510 to grounded contact 508.

In this connection, the set of springs designated RON are rotary off-normal springs which operate consequent to the first rotary movement of the shaft carrying wipers 521 to 524 and the set of springs designated ON5 are vertical off-normal springs which operate consequent to the first vertical movement of the said shaft.

A circuit can now be traced from grounded contact 508, armature 501, conductor 510, armature 537, armature 538, conductor 539, spring 540, to the winding of release magnet 15 Re5, causing the said release magnet to actuate and restore the shaft to normal position.

In this connection, it may be noted that shunted relay 541 is caused to actuate (but as will appear, to no operative purpose, due to spring set ON5 being normal) consequent to the attraction of armature 537, by reason of the spring set RON operating coincident with relay 517 and rotary magnet R5 actuating. A locking circuit for relay 533 is established consequent to its actuation from its lower winding armature 542, conductor 543, armature 544, conductor 510, contact 509 to grounded contact 508. At this juncture relays 502, 507, 527, and 533 of switch D are actuated and its shaft is at normal position.

Referring to switch E, when grounded armature 616 retracts a circuit can be traced from said armature 616, armature 630, armature 631, conductor 632, armature 633 to the winding of slow-releasing relay 634, relay 634 thus actuating and remaining so until its period after the last impulse is sent, when it will de-actuate. While relay 634 is actuated, its armature 635 serves to apply a short circuit between conductor 626, and armature 622 thus augmenting the current traversing the traced circuit including the windings of relay 801. Armature 627 retracting two times opens the traced circuit including the windings of relay 801 correspondingly, causing relay 801 to de-actuate and re-actuate two times coincident thereto. Upon the de-actuation of relay 634 following the sending of the two impulses from calling device 322, the short circuit placed upon the outside winding of relay 624 will be removed so that this winding will be again included in the traced circuit including the windings of relay 801.

At the time relay 601 actuated a circuit is established from grounded contact 618, armature 602, conductor 427, armature 637 to the inner winding of relay 624. The current traversing the inner winding of relay 624 is not of sufficient strength to operatively attract its armature 639. It will be borne in mind that the outer winding of relay 624 is included in the traced path including the windings of relay 801. However, the direction of current is opposite to that traversing the inner winding and is of such strength

that the core will not operatively attract armature 639. It will presently appear that upon a response being attained from the called telephone that the current traversing the outer winding of relay 624 will be reversed in direction consequent to the response. Under this condition of both windings energizing cumulatively the armature 639 will be operatively attracted for objects as will appear presently.

Upon relay 801 de-actuating two times, as referred to, a circuit is established from grounded armature 809, armature 815, armature 816, winding of slow releasing relay 817 to the winding of vertical magnet V9, causing it to step the shaft carrying wipers 818 to 820 two vertical steps into alignment with the second level of cooperating bank contacts, and there automatically rotate-in and seize the first set of bank contacts leading to a selector of a disengaged trunk, which in this case will be assumed as the first set 821 to 823. The operation of H, as to its automatic rotating-in and seizing function, is well known. Relay 824 will actuate to 90 effect the seizure so that the telephonic circuit will be extended from conductor 629 and 805 as follows: from conductor 629, armature 806, armature 808, conductor 824, wiper 819, bank contact 822, conductor 825 to the 95 upper winding of a relay in second selector J corresponding to relay 801 of selector H. Conductor 805 is continued to armature 804, armature 802, conductor 826, wiper 820, bank contact 823, conductor 827 to the lower winding of the said relay in selector J corresponding to said relay 801, the said latter relay actuating and preparing the circuits of the selector J to receive the impulse constituting the second digit "1" about to be sent. Remembering the condition of switch D last described, at this juncture relays 601, 605 and 617 of switch E are actuated and relay 824 of selector H is actuated. Also, relays in selector J corresponding to relays 801 and 810 of selector H. Relay 824 is held actuated in the well known manner due to receiving ground over conductor 828 (corresponding to conductor 813), bank contact 821, wiper 818, conductor 829, armature 830, conductor 831, armature 832, conductor 833, spring 834, winding of shunted relay 835, to grounded battery. However, the current traversing the traced path not being of sufficient strength to operatively affect relay 835, though its included relay 824 will be operatively affected.

Upon the calling subscriber manipulating his calling device 322 in accordance with the second digit "1" of the called number, causing one open impulse to be applied to the 125 traced path including telephone T2, relays 605 and 502 and also the relay in second selector J corresponding to relay 801, whereupon they will de-actuate and re-actuate one time responsive thereto. Referring first to switch 130

D, when grounded armature 506 retracts, a circuit can be traced from said armature, armature 515, armature 516, winding of relay 517, armature 518, conductor 520, to the winding of rotary magnet R5 causing the said rotary magnet to operate and advance wipers 521 to 524 one rotary position so that wiper 522 will stop, resting upon bank contacts 547. Relay 517 is caused to act in the manner as before described and unlock the described circuit including the lower winding of relay 527, whereupon relay 527 will de-actuate. Upon the de-actuation of relay 517 following the impulse to the rotary magnet a circuit will be established from grounded contact 508, armature 501, contact 509, conductor 510, armature 526, upper winding of relay 527, conductor 528, armature 529, conductor 530, wiper 522, bank contact 547, conductor 548, armature 549 to the upper winding of relay 550, causing said 550 (and said 527) to actuate and lock its lower winding through armature 553, conductor 510, contact 509, armature 501, to grounded contact 508. Relay 527 will be re-locked over the before described locking path. A path can also be traced from grounded contact 508 over the described path including armature 549 off-normal spring 551 to the winding of slow-actuating relay 552, causing said relay 552 to actuate and lock its winding through armature 526 to grounded conductor 510.

A circuit can now be traced from grounded contact 508, armature 501, conductor 510, armature 537, armature 538, conductor 539, spring 540 to winding of the release magnet Re5, causing the said release magnet to actuate and restore the shaft to normal position. At this juncture relays 502, 507, 527, 552, and 550 of the switch D are actuated, and the shaft is at normal position.

Referring to switch E, when grounded armature 616 retracts the one time responsive to the calling device 322, the same functioning in switch E will take place as before described when the first digit "2" was sent so that its functioning at this time will not be detailed. However, the selector J now controlled by armature 627, will be caused to function by stepping its shaft one vertical step into alignment with the first bank level thereof and automatically rotate-in and seize a set of dead bank contacts corresponding to a selector of the "1" thousand group of (second) selectors in the "2" main-branch office. However, inasmuch as the call is destined to a telephone in the sub-office and there is no "21" thousand in the main-branch office there is no particular interest in its operative effect upon switches in the "2" main-branch office, for it will appear presently that the trunk leading to the first selector H will be released incidental to sending of said digit "1".

In view of the previous description it is clear that coincident to selector J seizing in the manner set forth, relay 550 actuated and locked. Consequent to relay 550 actuating the circuit previously traced to the winding of relay 401 is opened by armature 512, causing it to de-actuate and open the traced path through the winding of relay 416, in turn causing the latter relay to de-actuate and disassociate conductors 431 and 322 at armature 430 and contact 433 respectively, and also unground wipers 403 and 404 due to the retraction of armatures 420 and 422 respectively. Relay 601 will retract its period after armature 422 retracts. This will open the traced energizing circuit of relay 605 and the latter's dependent relay 617 in turn, whereupon the ground existing on conductor 427 will be disconnected, rendering switch E normal and its leading-in conductors free and seizable as in the manner hereinbefore set forth. Incidental to relay 605 de-actuating and its armature 627 retracting the described energizing circuit including conductors 629 and 805 will be opened, and the dependent switches H, J, and K will restore to normal, and the busy ground will be removed from conductor 813 and its attachments. Thus, the trunk is again seizable to selectors N and P and to duplex lineswitches of the group containing B and C.

Bank contacts 554 and 555 are in multiple relation, tied to conductor 556, which is local to switch D. Therefore, ground potential is applied from conductor 510 through armature 557 to conductor 556 and to bank contacts 554 and 555. These latter bank contacts are engageable by wiper 521, which latter is tied electrically to private wiper 522. It is thus manifest that if wipers 523 and 524 are caused to engage bank contacts 558 and 559 or 560 and 561 respectively, regardless of whether private bank contacts 562 and 563 constitute ground potential, conductor 530 will receive ground from wiper 521. That is to say, that there is a false busy condition guarding line bank contacts 558 and 559, and 560 and 561 respectively against seizure under any conditions under the set-up condition now existing in the switch D, and therefore, connector F and its companion connectors of the group of connectors accessible to the two-hundred group of the "22" thousands group of subscribers' lines are barred against seizure. However, the bank contacts 564, and 555 engageable by wiper 521 do not constitute ground potential due to conductor 566, which is local to switch D, attached thereto being free of armature 557. Under this condition bank contacts 567 and 568, and 569 and 570 respectively will be seizable, wholly dependent upon whether private bank contacts 571 and 572 do not constitute ground potential respectively, which, as will appear, only ensues when the trunks leading from the

said sets of contacts are disengaged. Connector G being assumed to be disengaged, bank contact 571 will not constitute ground potential. It will be noted that connector 5 G has access to the called line leading to the telephone T7, which it will be recalled is in the "21" thousands group of subscribers' lines.

Referring again to connectors F and G it 10 will be manifest that since they are reached through the second levels of the switches D and E that they are each of the "2" hundreds group of the said "2" thousands and the said "1" thousands groups in the sub-office, respectively. That is to say, connector F has 15 access to the "2" hundred group of the "22" thousands group of the exchange and that the connector G has access to the "2" hundred group of the "21" thousands group of the 20 exchange.

It will be remembered here, that the second digit called by the calling subscriber was "1", and in view of the fact the next, or third digit that he will send is "2", and that the 25 switch D will be responsive thereto, functioning as a selector, it will cause its wipers 521 to 524 to automatically hunt on the second level of bank contact accessible to it, wherein the only connector not barred, by reason of the 30 position of armature 557, is connector G belonging to the "21" thousands group of subscribers. As will appear presently, the second digit sent by the calling subscriber not only releases the trunk leading to the "2" 35 main-branch office, but sets-up a condition in the switch D that constrains it to select connector G accessible to the "21" thousands group of subscribers' lines. Of course, it is understood that there are a plurality of 40 connectors such as G and F in their respective groups successively seizable, depending upon their busy or idle condition, with relation to other switches having common access to them, as has been referred to heretofore, so in the 45 subsequent descriptions reference will be made to the individual switches F and G as representative of their respective groups.

Upon the calling subscriber at telephone T2 50 manipulating the calling device 322 in accordance with the third digit "2", relay 502 will de-actuate and re-actuate two times responsive thereto, whereupon a circuit can be traced from grounded armature 506, armature 515, armature 516, winding of relay 517, armature 55 518 to the winding of the vertical magnet V5, causing it to operate two times and step the shaft carrying wipers 521 to 524 into alignment with the second level of bank contacts. At the time the vertical magnet V5 steps the 60 shaft from its normal position and the contact springs ON5 operate, a circuit can be traced from grounded conductor 510, armature 537, spring 574, to the winding of shunted relay 541, relay 541 actuating. A locking circuit 65 for relay 541 can be traced from grounded

off-normal spring 575, armature 576, armature 577 on the rotary magnet R5, spring 574 to its winding, and it will be borne in mind this can only exist when the off-normal springs ON5 are operated. When relay 517 70 de-actuates its period after the last impulse to the vertical magnet V5, a circuit can be traced from grounded conductor 510, armature 537, armature 579, spring 580 to the winding of rotary magnet R5, causing it to actuate and advance wipers 521 to 524 into engagement with bank contacts 554, 562, 558 and 559 respectively. Bearing in mind that bank contact 554 constitutes ground potential, received through armature 557, this ground will be conducted to wiper 521, conductor 530, armature 529, conductor 528, spring 581, conductor 582, armature 583, conductor 584, armature 577, spring 574 to the winding of relay 541, causing it to re-actuate, its previously 80 described locking circuit having been broken incidental to armature 577 on the rotary magnet R5 attracting incidental to it driving the shaft the first rotary step. Relay 541 being 85 actuated a circuit path can again be traced from conductor 510, armature 537, armature 579, spring 580 to the winding of rotary magnet R5, causing it to re-actuate and drive the wipers 521 to 524 into engagement with bank contacts 555, 563, 560 and 561 respectively. 90 Armature 577 attracting as before, incident to the operation of the rotary magnet R5, opens the hereinbefore described locking circuit for relay 541, whereupon due to wiper 521 finding ground on bank contact 555, received through armature 557, relay 541 is again caused to actuate in the manner before described when wiper 521 encountered ground on bank contact 554, whereupon rotary magnet R5 is again energized to drive wipers 521 95 to 524 into engagement with bank contact 564, 571, 567 and 568 respectively. Connector G being assumed to be disengaged, and therefore, bank contact 571 does not constitute ground potential, and the further fact that bank contact 564 does not receive ground over conductor 566 due to it being free of armature 557, the wiper 522, nor its companion wiper 521 does not apply ground potential to conductor 530 to cause relay 541 to re-attract. Also, conductor 584 does not now constitute ground potential as received from grounded spring 575 or over conductor 530 100 from one of wipers 521 or 522. Ground potential is removed from the upper winding terminal of relay 585, so that a circuit can now be traced from grounded conductor 319, winding of slow-actuating relay 585, conductor 584, armature 577, spring 574, to the winding of relay 541. Relay 585 will actuate its period after energization, but the winding of relay 541, which is in series relation to the winding of relay 585, is not energized sufficiently to operatively attract the armatures on said 105 110 115 120 125 130 541.

At this juncture relay 585 is the only relay in switch D actuated, relay 502 and its dependent relay 507 having de-actuated in sequence consequent to the actuation of relay 585. Armature 501 retracting removes ground potential from conductor 510, therefore, the locking circuit for relays 527, 552, 533 and 550 is open and the said relays de-actuate. It will be noted that armature 512 has now retracted against its resting contact, but since conductor 510 does not now constitute ground potential relay 401 will not be re-energized.

A circuit can now be traced from armature 503, conductor 504, previously traced path including telephone T2, conductor 320, armature 505, conductor 586, wiper 524, bank contact 568, conductor 587, to the upper winding of the line relay in connector G corresponding to line relay 701 in connector F, and from the lower winding thereof, to conductor 702, bank contact 567, wiper 523, conductor 588, to armature 503, the line relay in connector G actuating and causing its dependent slow-releasing relay corresponding to relay 703 in connector F to actuate and apply ground to conductor 704, bank contact 571, wiper 522, conductor 530, armature 529, conductor 528, spring 581, conductor 582, armature 583, to the lower winding terminal of relay 585 and conductor 319, and from the upper winding terminal of relay 585, conductor 584, armature 577, spring 574, to the winding of relay 541 maintaining relay 585 actuated. The relay 541 remains un-actuated due to it being under-energized because of the winding of relay 585 being included in the traced energizing circuit.

The detailed operation of the connector G will not be gone into at this time in view of the fact that it is similar to connector F, which is a well known form of connector, and also in view that it has been stated that the connector H of Fig. 2 of the cited patent to Newforth may be substituted for either connector G or F to meet the operative requirements of the present invention. However, it will be borne in mind that when the connector G is seized by switch D conductor 704 will have ground potential applied to it from within connector G and this ground potential is applied over the traced path to maintain relay 585 actuated and to maintain the ground potential on conductor 319 previously applied through armature 501 and grounded contact 508, so that relay 314 is maintained actuated, and the guarding ground potential is maintained on conductor 315, to prevent the calling line leading to telephone T2 from being intruded upon.

Upon the calling subscriber at telephone T2 sending the fourth digit "1" of the called telephone number, connector G will function to cause its wipers 712, 713, and 714 to be stepped up into alignment with the first

bank level thereof in readiness to receive the final two impulses constituting digit "2" of the called telephone number, whereupon the said wipers will be rotated-in into engagement with bank contacts 715, 716 and 717 respectively and the line leading to telephone T7 signaled upon in the well known manner.

Upon the called subscriber at telephone T2 responding after the sounding of bell 718 the calling and called subscribers are in telephonic relation over the circuits previously traced from the calling subscriber's telephone T2 to conductors 702 and 587, and from conductor 702, wiper 714, bank contact 717, conductor 719 through the telephone T7, conductor 720, bank contact 716, wiper 713 to conductor 587. Upon the calling subscriber at telephone T2 replacing his receiver, assuming that the called subscriber at telephone T7 has replaced his receiver beforehand, and thereby caused the relay in connector G corresponding to 721 in connector F to de-actuate and restore the original direction of current to the calling subscriber as contemplated in H of the cited patent to Newforth. The relay in connector G corresponding to 701 in connector F will de-actuate, whereupon dependent relay in connector G corresponding to 703 in connector F will de-actuate and remove ground potential from conductor 704 and complete an operative circuit from the grounded armature of the relay in connector G corresponding to 722 in connector F, off-normal spring in connector G corresponding to 723 in connector F, armature in connector G corresponding to 724 in connector F corresponding to the release magnet in connector G corresponding to Re7 in connector F, causing the restoration of connector G.

Ground being now removed from conductor 704 the energizing path for relay 585 will be open and it will de-actuate, whereupon a circuit will be completed from grounded armature 506, armature 515, armature 516, off-normal spring 591 to the winding of the release magnet Re5, causing it to actuate and restore the switch D to normal. It will be noted in this connection that an alternative path to spring 591 exists through spring 540. This latter spring is provided in case the subscriber at telephone T2 should replace his receiver after sending the first or second digits as set forth, and before sending the third digit, under which condition the set of springs ON5 would be normal, but the set of springs RON will be operated. Ground being removed from conductor 319, relay 314 will de-actuate, whereupon the circuits are in normal condition. That is, a new call can be initiated from telephone T2 and re-engages switch D in the manner heretofore described, or if the switch D has been seized by some other lineswitch of the group of which

lineswitch A is one, the lineswitch A by reason of bank contact 309 constituting ground potential will rotate off the set of bank contacts corresponding to switch D and hunt 5 for a disengaged switch in the group containing D, wherein wiper 306 will find the engaged bank contact ungrounded and seizable as before set forth.

It will now be assumed that in lieu of the 10 calling subscriber at telephone T2 desiring communication with telephone T7 that a connection is desired to telephone T7' the calling number of which is "22212". The calling subscriber will initiate the call in the 15 manner as before detailed, whereupon switch D will be seized and the duplex lineswitch in Fig. 4 will engage switch E and the connection will be extended to the incoming first selector H in the "2" main-branch office as before. The sending of the first digit "2" will 20 operate the selector H in the manner before detailed, whereupon it will again select second selector J. The switch D will function as before described coincident with the operation of the selector H.

Upon the second digit "2" being called, selector J will function in the manner as before set forth, only in this instance, its wipers will be stepped up into alignment with the 30 second bank level thereof in lieu of the first level thereof, and there rotate-in and seize a set of dead bank contacts corresponding to a selector of a "2" thousand group of (second) selectors in the "2" main-branch office. 35 However, inasmuch as the call is destined to a telephone in the sub-office, and there is no "22" thousand in the main-branch office there is no particular interest in its operative effect upon switches in the "2" main-branch 40 office, for it will appear presently that the trunk leading to the first selector H will be released consequent to the said digit "2" being sent as before set forth wherein the second digit was "1" and the call was completed 45 directly from switch D through a connector (G) to the called line in the sub-office.

Bearing in mind that switch E, consequent to digit "2" being sent will function in a manner as when digit "1" was sent, only that 50 in this instance relay 605 will de-actuate and re-actuate two times instead of one time, attention will be directed to the operation of switch D, bearing in mind that as in the previous call, the sending of the first digit 55 "2" from calling device 322 caused relays 502, 507, 527 and 533 to be actuated. Upon the second digit "2" being sent the wipers 521 to 524 will be caused to be driven by rotary magnet R5 in the manner as before set forth, only that they will be advanced two rotary positions in lieu of one rotary position, that is, wiper 522 will rotate into engagement with bank contact 525, a second time, instead of rotating only into engagement 60 with bank contact 547. Upon relay 65

517 de-actuating its period after the second impulse of the second digit "2" is imparted to the rotary magnet R5, a circuit can be traced from grounded conductor 510, armature 526, upper winding of relay 527, armature 529, conductor 530, wiper 522, bank contact 525, conductor 531 make-before-break spring 532, armature 592, armature 593, conductor 594, armature 595 to the upper winding of relay 596, relays 527 and 596 actuating. Relay 527 will lock through its armature 534, armature 536, to grounded conductor 510 as before described. In this connection it is manifest that at the time relay 517 70 actuated upon the first impulse of the second digit "2" being sent, armature 536 opened the locking circuit of relay 527, said 527 de-actuating. Relay 596 will lock its lower winding through its armature 597 to grounded conductor 510. Upon the actuation of relay 527, the before described energizing circuit 75 through its armature 538 to the release magnet Re5 will be completed, causing the wipers 521 to 524 to be restored to their normal position. In this connection it is to be noted 80 that armature 593 on relay 527 attracts and opens the connection to conductor 594 before the release magnet Re5 is effective to restoring the wipers as set forth and, therefore, as wiper 522 engages bank contact 525 85 for an appreciable period, unless armature 593 is attracted before armature 595 has completed its engagement to its co-operating contact when wiper 522 first engaged bank contact 525, a circuit would be established 90 over conductor 594, armature 595 to the upper winding of relay 596, and cause the said relay 596 to be falsely actuated. Of course, the said relay 596 can be adjusted stiffly or 95 have a retarded actuating characteristic so 100 that it would not operatively energize even if armature 595 had engaged its co-operating contact for a brief interval before armature 593 disengaged its resting contact. However, it will be manifest that in the last exampled call, wherein the first two digits are 105 "22", that the function of armature 593 described would have no bearing since relay 596 is caused to be actuated on the second digit being sent, though in the exampled call 110 wherein the second digit is "1", the relay 596 remains normal.

Relay 552, due to its slow-actuating characteristic, will not actuate from the circuit 115 established from grounded conductor 510, conductor 548, armature 549, spring 551 to its winding, wherein its armature 542 opens the locking circuit of relay 533, until relay 596 has actuated to establish the circuit from 120 grounded contact 598, spring 551 to the winding of relay 552. A locking circuit from the winding of relay 552 is established to its armature 526 as before traced. At this junction 125 relays 502, 507, 527, 552, 550 and 596 of switch D are actuated.

The actuation of relay 550, as before described causes relay 416 to de-actuate, whereupon switch E, the trunk leading to the "2" main-branch office, and the switches described as operated therein, are restored to normal condition as before set forth consequent to conductor 513 becoming ungrounded incident to the completion of the series of impulses constituting the second digit "2" of the called number wherein the first digit and the second digit were pertinent to the telephone number of a subscriber in the sub-office.

Upon the calling subscriber at telephone T2 manipulating the calling device 322 in accordance with the third digit "2", the same functioning of switch D will ensue as before described when the third digit "2" was sent. However, it is to be borne in mind in this connection that, in addition to the relays actuated under the condition when the third digit "2" was sent in the hereinbefore description wherein the second digit was "1", relay 596 is now actuated. So in the present instance then, conductor 556, and its attached bank contacts, do not constitute ground potential, but that conductor 566 and its attached bank contacts 564 and 565 do constitute ground potential, applied by armature 557. It will thus be clear in view of the foregoing explanation and descriptions that switch D, through its wipers 523 and 524, is barred from seizing bank contacts 567 and 568, and 569 and 570 respectively, due to the fact that bank contacts 564 and 565 constitute ground potential and that this condition of being barred is irrespective of the state of bank contacts 571 and 572 engageable to wiper 522. Thus the trunk consisting of telephonic conductors 587 and 702 and private conductor 704 leading to connector G belonging to the "2" thousands group in the sub-office is barred against seizure and that bank contacts 562, 558 and 559 leading over conductors 501', 502' and 503' respectively to connector F are seizable. Should connector F be in a seized state when wiper 522 engages bank contact 562 and, therefore, encounters ground potential on said bank contact 562, as will appear, the switch D will be caused to function as before set forth wherein wiper 521 similarly encountered a bank contact which applied ground potential to conductor 530. The wipers 521 to 524 will thus be advanced a rotary step into engagement with bank contacts 555, 563, 560 and 561 respectively. Should bank contact 563 constitute ground potential the said wipers 521 to 524 will be caused to advance an additional rotary position in the manner as before. It will now be assumed that connector G is idle and, therefore, bank contact 571 does not constitute ground potential. Were it not for the fact that bank contact 564 constitutes ground potential received through armature 557, the

switch D would seize, completing the connection from the calling subscriber at telephone T2 to connector G in the manner before detailed. However, the ground potential received from bank contact 564 applied to wiper 521 and conductor 530 will operate to again cause the wipers 521 to 524 to be advanced into engagement with bank contact 565, 572, 569 and 570 respectively, where, due to the bank contact 565 constituting ground potential the same functioning will take place wherein the wipers will be advanced from the last engaged bank contact to a successive set, not shown, the operation continuing until neither of wipers 521 nor 522 receive ground potential from an engaged bank contact, when the switch D will seize in the manner as before set forth.

Returning to the condition wherein wipers 521 to 524 engage bank contact 554, 562, 558, and 559 wherein bank contact 562 did not constitute ground potential and that the switch D therefore, seizes. Relay 585 actuates, and relay 502 and its dependent relay 507 de-actuates in sequence. Conductor 510 becomes ungrounded, whereupon relays 527, 552, 550 and 596 will become unlocked and de-actuate. The telephonic circuit from the calling telephone T2 previously traced to armatures 503 and 505 is now continued from armature 503, conductor 588, wiper 528, bank contact 558, conductor 502', make-before-break spring 735 to the upper winding of relay 701 and from the lower winding of relay 701, make-before-break spring 736, conductor 503', bank contact 559, wiper 524, conductor 586 to armature 505, relay 701 actuating. A circuit can now be traced from grounded armature 737 to the winding of slow-releasing relay 703, 703 actuating. Grounded armature 722 applies ground potential to conductor 501', bank contact 562, wiper 522, conductor 530, armature 529, conductor 528, spring 581, armature 583 to the lower winding of relay 585 and conductor 319. Due to the slow-releasing characteristic of relay 507 the said ground potential received from armature 722 is applied to conductor 319 before armature 501 retracts, and therefore, no lapse of ground potential occurs to conductor 319. It has been set forth hereinbefore how relay 585 and relay 314 are maintained under this condition, as well as the fact that the line leading to telephone T2 and the trunk leading to switch D is barred against seizure by switches having common access thereto as has been set forth.

Relay 585 being now the only relay in switch D actuated, the telephonic conductors 504 and 320 are continued without affecting attachments to the terminals of the windings of relay 701. Upon the calling subscriber at telephone T2 manipulating the calling device 322 in accordance with the fourth digit "1" of the called line leading to telephone T7', relay 701 will de-actuate and re-actuate

one time, applying ground from its armature 737 through armature 738, armature 739, winding of slow-releasing relay 740, winding of vertical magnet V7, sideswitch wiper 741 to grounded battery. Relay 740 will attract its grounded armature 742 and apply the ground to the winding of private magnet P7, causing it to actuate preparatory to permitting the sideswitch wipers 741 and 743 to advance into their second position. The vertical magnet causes the wipers 745 to 747 to be raised one vertical step into alignment with the first level of bank contacts. Upon the period of relay 740 elapsing following the operation of the vertical magnet wherein the armature 742 retracts and the sideswitch wipers 741 and 743 advance into their second position, the connector F is in condition to receive the fifth or final digit "2" of the called number appertaining to telephone T7'. Upon the calling subscriber at telephone T2 manipulating the calling device 322 in accordance with digit "2" relay 701 will be caused to de-actuate and re-actuate two times responsive thereto, whereupon armature 737 will apply its ground through armature 738, armature 739, winding of relay 740, armature 749, winding of rotary magnet R7, sideswitch wiper 741 to grounded battery, causing the wipers 745 to 747 to be rotated two steps into engagement with bank contacts 751 to 753 respectively. Assuming the line leading to telephone T7' to be disengaged, and therefore, bank contact 751, does not constitute ground potential upon relay 740 retracting the sideswitch wipers 741 and 743 will advance into their third position and complete a circuit from ground, wiper 743, winding of relay 755, wiper 741 to grounded battery, relay 755 actuating. Ground through wiper 743 is also applied to wiper 745 and bank contact 751 to operate the lineswitch cut-off relay 760 and place a ground potential on the private contacts in multiple with bank contact 751 to guard the line seized by connector F against intrusion through other accessible connectors. Interrupted ringing current from source G7 is applied through armature 761, armature 762, wiper 747, bank contact 753, conductor 763, through signal bell 764, condenser 765 of telephone T7', conductor 766, bank contact 752, wiper 746, armature 767, armature 768, inside winding of relay 769 to grounded battery, signal bell 764 operating. Relay 769 is not operative from the interrupted ringing current traversing it, but it is operative to the direct current which will traverse it upon the receiver being removed by the called subscriber at telephone T7'. Upon the called subscriber responding and relay 769 operatively energizing, a circuit can be traced from grounded battery through its outside winding, armature 770 to grounded off-normal spring 771

of set ON7, which latter operated upon the shaft carrying wipers 745 to 747 stepping off-normal. Relay 769 is thus locked actuated and the ringing current source G7 is disassociated. Ground from spring 771 is applied through armature 770, lower winding of relay 721 to conductor 772, armature 761 over the described path including the receiver of telephone T7' to armature 768, conductor 773, to the upper winding of relay 721, causing it to actuate and transpose the described relationship of conductors 502', and 503' with relation to the windings of relay 701, so that the current now projected through the receiver of the calling telephone T2 is reversed in direction. The calling telephone T2 and the called telephone T7' are now in telephonic relation.

Assuming that the receiver at telephone T7' is now replaced, and following this operation the receiver at telephone T2 is replaced. Relay 721 de-energizes and de-actuates resultant to the receiver at telephone T7' being replaced and prepares the circuit from the winding of release magnet Re7 at its armature 724 so that when relay 703 de-actuates following the de-actuation of relay 701, resulting from the receiver at telephone T2 being replaced, a circuit is established from the winding of the release magnet Re7, armature 724, spring 723, to grounded armature 722, the release magnet operating to restore the connector to normal position. At the time armature 722 retracts it removes ground potential from conductor 501' and, therefore, de-energizes relays 585 and 314, whereupon they retract and restore switches D and E to normal respectively. The circuits are now in normal condition.

It has been stated that the connector F belongs to the "2" thousand group in the sub-office, that is, has access to the subscribers' lines, the telephone numbers of which have "22" as the first two digits thereof as distinct from the connector G belonging to the "1" thousand group in the sub-office, that is, has access to the subscribers' lines, the telephone numbers of which have "21" as the first two digits thereof. It is now clear that incidental to the operation of the switch D responsive to the second digit "2" a condition is set up in the said switch D which adapts the said switch D to seize connector F (and connectors of its group) and bars it from seizing connector G (and connectors of its group) upon the third digit being sent, which in the call exemplified, was digit "2". Switch D thus has access to either the "2" hundred group of connectors of the "2" thousand group of the "2" hundred group of connectors of the "1" thousand group, depending upon a set-up condition in the D switch effectuated incidental to the sending of the second digit of the number called.

If it is desired to have the sub-office con-

tain the "21" and the "23" thousand groups of subscribers' lines in lieu of the "21" and the "22" groups of subscribers' lines, for example, the conductor leading to armature 593 would be disassociated from it and from armature 592 and the conductor leading to the contact upon which armature 593 rests would be disassociated from conductor 594. Conductor 594 will then be connected to bank contact 504'. Under this condition if the second digit of the number called were "3" in lieu of "2" the traced circuit through armature 595 would be established to set the switch in the manner described in relation to the condition wherein the second digit was "2". Of course, in this case, connector F would refer to the "23" thousands group of subscribers' lines instead of the "22" group.

Assuming now that with the switch D wired as last assumed, that is, conductor 594 is attached to bank contact 504' and the second digit called is digit "2". As before, upon wiper 522 resting on bank contact 525, when relay 517 retracts following the "2" digit series of impulses, no circuit path including conductor 581 can be completed, due to armature 592 being disassociated and, therefore, the primary actuating circuit of relay 527 is not energized to attract armature 538 to prepare the circuit to the release magnet Re5 or to cause relays 596, 550 and 552 to actuate and lock. Under this condition relay 502, 507 and 533 will be the only relays in switch D that are actuated, and moreover, they will only remain actuated for the period of relay 517, as will appear.

Upon the retraction of relay 517 following the wiper 522 stopping upon bank contact 525 in the manner as before fully described and wherein relay 527 was caused to actuate and lock, restoring the switch D to normal position, the relay 527 caused its grounded armature 506' to apply ground potential to conductor 584 before relay 585, due to its characteristic and adjustment will actuate because of a possible lapse of ground potential removed consequent to the retraction of armature 537. Armature 506' therefore, applies a ground short circuit to the upper winding terminal of relay 585 practically coincident with the retraction of armature 537 which has maintained ground potential thereon by way of armature 577, or more exactly, prevented the winding of relay 585 from becoming included in series relation with the winding of relay 541. In this connection, the armatures 529 and 537, and co-operating contacts are so adjusted that the circuit including the upper winding of relay 527 and armature 529 is established before armature 537 retracts from its working contacts. This adjustment together with the characteristic given relay 585 insures that there will be no lapse of ground potential

on the upper winding terminal of relay 585 of sufficient duration for it to actuate.

In relation to wiper 521 being stopped resting on bank contact 525 in the last assumed instance wherein a circuit path could not be completed over conductor 531 due to armature 592 being disassociated from its connections shown in the drawings, the upper winding of relay 527 is not energized and, therefore, does not actuate and lock as in the instances exemplified wherein wiper 522 completed a circuit, operative on the retraction of armature 529. Under this condition armature 506' does not attract and apply ground potential to conductor 584. Therefore, upon the retraction of armature 537 its period after wiper 522 is stepped into engagement with bank contact 525 no ground short circuit will thereafter exist with relation to conductor 584. Under the last condition a circuit can be traced from the winding of relay 541 rotary off-normal spring 578, armature 577, conductor 584, winding of relay 585, conductor 319, conductor 418, armature 420, wiper 403, bank contact 407, conductor 426, conductor 427, armature 602 to grounded contact 618, relay 585 actuating. It will be recalled that under the series condition of windings of relays 541 and 585, relay 541 will not actuate and, moreover, if it did, would be to no operative purpose by reason of off-normal springs ON5 being in normal position due to the shaft not having stepped vertically off-normal. Relay 502 becomes disassociated at armatures 503 and 505, whereupon it will de-actuate, followed by relay 507 in sequence. Ground potential being removed from conductor 510 the described locking circuit of relay 533 is opened. At this juncture, with relay 585 being the only relay in switch D actuated, telephonic conductors 504 and 320 are continued over conductors 588 and 586 to wipers 523 and 524 respectively which are resting on bank contacts 507' and 508' respectively, and in view of bank contacts 507' and 508' being dead there is no condition in switch D which affects the telephonic conductors 322 and 431 leading through the duplex lineswitch element B, reciprocal-functioning switch E, first selector H, second selector J rotated-in on its second bank level in seized relation to third selector K. It will be noted that due to the armature 512 being retracted ground potential received from conductor 319 is maintained on conductor 513, holding relay 401 actuated and, therefore, its dependent relay 416 also.

As under the last assumed condition where-in conductor 594 was attached to bank contact 504' and wherein armature 592 was disassociated from its attached conductor, the "23" thousands group of subscribers' lines will terminate in the "2" main-branch office, or subordinate to it, in an independent sub-

- office or contiguous to the sub-office containing D and E, and they would not be accessible through connectors that are directly accessible to the wipers of switches D and E.
- 5 Referring again to the traced call to telephone T7' gained by calling telephone number "22212", it will be assumed that the call has been directed to telephone T11 to be gained by calling telephone number "23111".
- 10 The functioning of the various switches will be as before described consequent to the first digit "2" being sent wherein relay 314 in switch A; relays 502, 507, 527, 533, in switch D; relay 416 in switch element B, and auxiliary relay 401 in Figure 4; relays 601, 605 and 617 of switch E; relay 824 in switch H and relays in second selector J corresponding to 801 and 810 will be actuated. Upon the second digit "3" being sent selector J
- 15 will function in the manner as before referred to and rotate-in on its third level and seize third selector K, whereupon relays corresponding to 801 and 810 will become actuated in K and a relay corresponding to 824 will become actuated in J. The functioning of switch E controlling the operation of selectors H and J will be as before clearly set forth in relation to digits "22" and "21".
- 20 Returning now to switch D, the operation wherein the wipers thereof are caused to be rotated normally will be as before set forth, the wipers being rotated three steps, wiper 522 resting upon bank contact 504'. The latter bank contact is dead and, therefore, relay 527 will not be caused to actuate and lock and release wipers to normal position, nor apply ground from its armature 506' to conductor 584. Relay 585 will, therefore, actuate and disassociate the operative circuit in
- 25 switch D so far as affecting telephonic conductors 504 and 320 is concerned as before set forth, so that the connection is now a direct connection through switch E functioning as a trunk repeater, first selector H, second selector J, terminating in second selector K. Upon the calling subscriber at telephone T2 sending the third digit "1" selector K will function to step its wipers 832 to 834 up one level and into engagement with
- 30 bank contacts leading over conductors 835 to 837 to connector L. Upon the calling subscriber next sending the fourth digit "1" the connector L will step its wipers 838 to 840 up one level into alignment with the first
- 35 level of bank contacts, and upon the calling subscriber sending the fifth (last) digit "1" the said wipers 838 to 840 will rotate-in into engagement with bank contacts 841 to 843, whereupon the connector L will seize and ring
- 40 upon the line leading to telephone T11, in a manner as fully set forth in relation to connector F, cut-off relay 844 disassociating contacts 845 and 846. Upon the called subscriber at telephone T11 responding by
- 45 removing the receiver from the switchhook, connector L will function as set forth under a similar condition with relation to connector F, whereupon the current traversing the trunk conductors 629 and 805 will be reversed in direction in the manner as referred to under a similar condition with relation to connector F. Relay 634 being normal, the outside winding of relay 624 will be included in the circuit including conductors 629 and 805, and terminating in the windings of a relay in connector L corresponding to relay 701. Therefore, the outside winding of relay 624 will now energize its core cumulatively with the inside winding thereof. Under this condition armature 639 will be attracted against its co-operating grounded contact, causing relay 640 to actuate, which will reciprocate the normal relationship previously existing between conductors 428 and 435 and conductors 608 and 612 respectively so that the current traversing conductors 428 and 435 including the calling telephone T2 will now derive current from the windings of relay 605 in the reversed direction to that primarily established. It is thus clear that upon the connector L reversing the direction of current projected back over its leading-in trunk including the outside winding of relay 624 a secondary functioning ensues which causes the current traversing the circuit including the calling telephone T2 to be coincidentally reversed, indirectly. It will follow from the foregoing that if the called subscriber at telephone T11 replaces the receiver, whereupon the connector L will function to establish the initial direction of current flow back over its leading-in conductors including the outside winding of relay 624, armature 639 will retract, followed by the de-actuation of relay 640, whereupon the current projected over conductors 428 and 435 and including the calling telephone T2 will be re-established as it existed primarily upon the initiation of the call. The object of thus reversing current direction is for supervisory purposes to subscribers' lines where this function is desired, and is provided anticipating such requirements on a portion of the subscribers' lines. Upon the actuation of relay 640, its armature 622 removes the short-circuit from around the resistance connected between armature 622 and conductor 621, so the outside winding of relay 624 will then have an auxiliary resistance included with it in bridge of the telephonic conductors and thus affect telephonic transmission to a less degree than were no such obstruction included. After the armature 639 is attracted the lower energization of relay 624 will retain armature 639.
- 50 Upon the calling subscriber replacing the receiver, relay 605 will de-actuate followed by its dependent relay 617. Armature 627 retracting opens the energizing circuit including conductors 629 and 805 and the relay
- 55 70 80 85 90 95 100 105 110 115 120 125 130

in connector L corresponding in 701 in connector F will restore, and dependent thereon, selectors H, J and K will restore. Armature 602 retracting removes ground potential 5 from conductor 427, conductor 426, bank contact 407, wiper 403, armature 420, conductor 418, conductor 319. Thus, the energizing circuit of relays 416, 401, 314, 585 and 601 is opened, causing them to deactivate, where- 10 upon the circuits and switches are in normal condition, bearing in mind, that when relay 585 deactuates a circuit can be traced from grounded armature 506, armature 515, armature 516, spring 540 to the winding of the 15 release magnet Re5, causing the wipers of switch D to be restored to normal position.

Returning to the condition assumed wherein a calling subscriber at telephone T2 initiates the call whereupon relays 502 and 507 20 are caused to actuate, and ground is applied to conductor 319 by armature 316, followed by a ground from armature 501. Conductor 513 is grounded through armature 512. Relay 401 actuates followed by relay 402, as 25 suming that bank contact 407 constitutes ground potential, upon relay 401 actuating a circuit can be traced from the winding of motor magnet M4, armature 412, armature 414, armature 440, armature 420, wiper 403 30 to grounded bank contact 407. Motor magnet M4 will actuate and advance the wipers 403 to 406 one step upon its de-actuation, whereupon if bank contact 441 constitutes ground potential the functioning described 35 will be repeated, and so continued until an ungrounded bank contact is encountered by wiper 403, when it will seize as hereinbefore set forth. The successive sets of bank contacts, it will be borne in mind, lead to switches 40 in the group to which E belongs and, as will appear, the conductor 426 and multiplied bank contacts corresponding to 407 and 442, will constitute ground potential when its corresponding switch, E for example, is busy, or 45 as will appear presently, the trunk associated with said E is engaged by having been seized at the main-branch office end. Therefore, upon the call being initiated at telephone T2 element B will forthwith seize a switch corre- 50 sponding to E, or it will start rotating, hunting for an idle said switch.

Referring to element C of the duplex lineswitch it is now clear that should switch E become busy by reason of some other duplex 55 lineswitch of the group containing elements B and C (or if the trunk leading to switch E from the "2" main-branch office is seized at the main-branch office end, as will appear presently), conductor 427 will constitute ground potential and, therefore, bank contacts 407, 442 and multiples thereof will constitute ground potential. In a similar manner, if a switch of the group containing E and corresponding to conductor 443 and bank 60 contacts 444 and 445 becomes busy, the said

444 and 445 and multiples thereof will constitute ground potential. Assuming now that bank contact 445 becomes grounded because of a condition as last referred to ensuing, a circuit can be traced from winding of motor 70 magnet M'4, armature 446, armature 447, armature 448, wiper 449 to said grounded bank contact 445, motor magnet M'4 actuating and opening the traced circuit at its armature 446, whereupon the driving armature of motor magnet M'4 will retract and drive wipers 449 to 452 one rotary step into engagement with bank contacts 442, 453, 454 and 455 leading to conductors 426, 423, 429 and 434 respectively, to switch E. If wiper 75 449 encounters ground potential of bank contact 442, the last before traced circuit including the winding of motor magnet M'4 to ground will be re-established, causing the wipers 449 to 452 to be advanced a further 80 rotary step, this function continuing until wiper 449 fails to find a completing ground, whereupon the switch will remain in normal condition and, therefore, in an unseized condition. It is manifest that should the bank 85 contact upon which wiper 449 last rested upon as ungrounded, should become grounded by reason of a busy condition to the corresponding trunk ensuing, the motor magnet M'4 would become energized as before described 90 and start the switch functioning, automatically hunting for an idle set of bank contacts upon which to rest. It will thus appear that the switch element C will at all times 95 automatically function in order to keep its 100 wipers resting upon an idle set of bank contacts, the object of which will appear presently. It will be noted that under the conditions wherein wiper 449 constituted ground potential that a circuit from the winding of relay 460 can be traced to armature 461 and to ground through said wiper 449 and, therefore, relay 460 will be actuated while the element C functions automatically as set forth, 105 in order to be resting upon a set of idle bank contacts. Under the condition of relay 460 being actuated, a circuit can be traced from grounded armature 462 to conductor 418 which leads over conductor 319 to bank contact 309 and its multiples, so under the condition of the duplex lineswitch elements not being seized by lineswitch A, or a lineswitch of the group containing A, the duplex lineswitch Fig. 4 will be guarded against seizure 110 during the time that its element C may be automatically functioning as set forth. That is to say, if element C does not have its wipers resting upon an idle set of bank contacts, the duplex lineswitch Fig. 4, containing elements 115 B and C, is guarded against seizure by reason of it having a false busy condition applied to its leading-in conductors.

It will now be assumed that upon the lineswitch A seizing the duplex lineswitch Fig. 4 that wipers 403 to 406 were resting upon bank 120 125

contacts of an engaged trunk, that is, that some other duplex lineswitch is operatively co-operating with switch E, or that the trunk leading to switch E is busy, by having been seized at the main-branch office end. Under this condition bank contact 407 will constitute ground potential and, therefore, element B will start rotating, hunting for an idle set of bank contacts, as has been clearly described hereinbefore.

At the time relay 401 actuates consequent to the seizure of the duplex lineswitch Fig. 4, ground potential was described as being applied through armature 413 to the winding of relay 402. Ground is also applied to its multiplied slow-actuating relay 465, causing it to attract its armature 466 at its period thereafter, completing a circuit from grounded conductor 418, armature 411, armature 466, to the lower winding of relay 467. The relay 465, due to being slugged or otherwise retarded, will not attract its armature 466 until motor magnet M4 has advanced the wipers of element B a pre-determined number of steps. Upon the armature 466 becoming attracted a circuit can be traced from the winding of motor magnet M'4, armature 446, armature 447, winding of relay 467, armature 466, armature 411, to grounded conductor 418, relay 467 actuating. Motor magnet M'4 will not operatively energize over the latter described path due to the inclusion of the winding of relay 467. Upon relay 467 actuating a circuit can be traced from conductor 431, armature 468, conductor 469 to wiper 451, and from conductor 322, armature 470, conductor 471 to wiper 452. If it is assumed that wipers 449 to 452 are resting upon bank contacts 442, 452, 354 and 455 respectively, at the time relay 467 actuates, the traced circuit to wiper 451 will be completed to conductor 429 and conductor 428 to make-before-break spring 609 of switch E, and from wiper 452, conductor 434, conductor 435 to make-before-break spring 610 of switch E. The relationship of calling telephone T2 to switches D and E are thus the same under the present condition of element C having seized as when element B was described as seizing.

At the time relay 467 actuates and attracts its armature 414 it opens the described energizing circuit of motor magnet M4 and, therefore, incapacitates the element B from functioning further. And it also is clear that after element B seizes as has been set forth hereinbefore, the energizing circuit of motor magnet M'4 is opened so that in the event element B has seized, element C is incapacitated from functioning automatically, should its wiper 449 rest on a bank contact element B was described as seizing.

It is thus clear that upon the seizure of a duplex lineswitch by a lineswitch as A, element B will seize if its wipers are resting upon a set of bank contacts of an idle trunk,

and if the trunk leading from the contacts upon which they rest is busy, it will start rotating, seeking an idle trunk, and if it does not encounter an idle set of bank contacts after rotating its pre-determined number of steps, the element C will seize. However, if the element C should have started rotating automatically after the element B started rotating and before the termination of the pre-determined period for element B to hunt, before element C is capacitated by it (B) to seize, both elements B and C will be in the process of hunting. Then, in view of the hereinbefore descriptions, it is clear that the first element B or C to encounter an idle set of bank contacts will seize and thereupon incapacitate its companion element.

As has been stated at the outset, that in commercial systems it would sometimes be found advisable to have the elements corresponding to C of the duplex lineswitches accessible to switches of the group containing E which are not accessible to the elements corresponding to B and, therefore, the likelihood of the elements C automatically functioning under a non-seized condition of the duplex lineswitch, or of not resting upon a set of idle contacts after element B has rotated over the predetermined number of busy contact sets, after the seizure of the duplex lineswitch, will be remote and unlikely to often occur. Therefore it is practically assured that after a lineswitch as A seizes, a very brief interval of hunting by the duplex lineswitch seized will ensue, further insuring that the seizure of switch E, or other switch of its group seized, will have transpired before the calling subscriber has started the series of impulses constituting to the first digit of the called telephone number.

In the event the element C has access to an independent group of trunks as referred to, it may also have access to the same group as element B. Inasmuch as element B will not have access to the extra trunks to which element C has and that the element C will always rotate its wipers off a busy bank contact the elements C of the group will normally progress, under traffic conditions, until the extra group is reached. This is assuming that the group accessible to element B has idle trunks constantly, and that therefore the elements C are not called upon to seize. In commercial installations the practice would usually be to intersperse the extra trunks accessible to elements C only, so as to insure elements C will seize trunks in the main group as far as possible and to forestall a condition wherein the elements C will not have access to an idle trunk while elements B may have, but would be barred against seizing under the condition of element C not having access to an idle trunk. Under the latter method of connecting the trunks the armatures corresponding to 648

of all switches E which are in access to element C will be chained as shown in Fig. 8, and under such condition the conductors attaching bank contacts 480, 485 and 486 to conductors 482, 484 and 487 respectively 60 may be disconnected.

Referring to armature 648, and the armatures shown in Fig. 8 located on the corresponding relays of switches corresponding to E of the group containing E, it will appear that when all the switches of the group containing E are busy by reason of being seized from the sub-office end, or in the main-branch exchange end, these armatures will 10 all be attracted and close a circuit from the winding of common relay 475 to the grounded contact G8 on the last switch of the group. That is to say, when all the trunks of the group corresponding to the switches of the group containing E are busy from the condition of having been seized from the sub-office end, or the main-branch office end, relay 475 will be caused to be actuated, attracting the grounded armature 476 from 20 its resting contact, and unground the common conductor 477. A relay such as 475 is common, therefore, to the group of duplex lineswitches having access to the group of switches of which E is one. Ordinarily 30 there would be more duplex lineswitches than switches as E. Each duplex lineswitch has a relay corresponding to 478 of the duplex lineswitch containing elements B and C. Relay 479 is a relay corresponding to relay 35 478, but belongs to a different duplex lineswitch, not shown.

It will now be assumed that upon the calling subscriber initiating the call, that lineswitch A seizes the duplex lineswitch shown in Fig. 4, and that there are no idle trunks leading from any of the bank contact sets accessible to either elements B or C, and, therefore, a call can not be completed 40 destined to a subscriber reached through the 45 "2" main-branch office.

In this connection it will be noted that bank contact 480 and its multiplied bank contact 481 are normally locally grounded (not common to other duplex lineswitches of the 50 group containing elements B and C) over conductor 482, armature 483, common conductor 477 to grounded armature 476 and that, therefore, the sets of wipers belonging to element B and C will normally pass over 55 the sets containing bank contacts 480 and 481 respectively, as busy sets. However, under the condition of the chain-ground being completed through armature 648, and the armatures shown in Fig. 8 to ground G8, wherein 60 all the trunks of the group containing switch E are busy, armature 476 is attracted, thus removing the ground potential normally existing on bank contacts 480 and 481. Under this condition the first element B or C to have its 65 wiper 403 or 449 engage bank contact 480 or

481 respectively, under a seized condition of the trunk leading to the duplex lineswitch Fig. 4, will itself seize as if an idle set of trunk bank contacts were encountered. Assuming that element B, for example, seizes 70 the set of bank contacts containing bank contact 480, a circuit can now be traced from the winding of relay 478, local conductor 484, bank contacts 485 and 486, wiper 404, armature 422, armature 420 to grounded conductor 418. Wiper 403 will apply ground to bank contact 480, conductor 482 to armature 483, received from conductor 418, armature 420, armature 422. This would falsely ground conductor 477 were it not for the fact that armature 483 is now attracted so that conductor 477 will not constitute ground potential, depending upon whether the said chained armatures controlling relay 475 are all not closed. Under this condition (of relay 478 80 being actuated) the calling subscriber at telephone T2 will perceive a special tone applied from grounded tone source T4 over common conductor 487, bank contact 486, wiper 406, contact 433, conductor 322, conductor 320, bank contact 311, wiper 308, over the described path including telephone T2, wiper 307, bank contact 310, conductor 504, armature 503 through the upper winding 90 of relay 502 to grounded battery. This 95 special tone will index to the calling subscriber that all trunks to the main "2" main-branch office are busy, and that it will be fruitless to manipulate the calling device 322 by way of an attempt to call the wanted telephone number. 100

In this connection it will be noted that since there are no operative attachments associated with conductors 431 and 322 should the calling subscriber at telephone T2 know that the wanted telephone line belongs to the sub-office, he may ignore the special tone (received from T4) and proceed with the calling of the wanted telephone line, whereupon the switch D will function in a normal manner in linking the connection to a local connector, as F or G, and to the wanted telephone line. However, in the case of an assumed call to telephone T11 in the "2" main-branch office the calling subscriber will not be enabled to complete the call and he would, therefore, replace the receiver, whereupon relays 502 and 507 will deactivate in sequence, removing the ground potential from conductors 319, 418, 510 and 513. Relay 401 will deactivate followed by relay 416 and 478, whereupon the 110 circuits, concerned in relation to switches A, D and duplex lineswitch Fig. 4 are in their 115 normal state.

Assuming that element C, for example, 120 seizes the set of bank contacts containing bank contact 481, if said 481 is ungrounded as set forth upon the calling subscriber at telephone T2 initiating the call, wherein all the trunks 125 accessible to the duplex lineswitch Fig. 4 are 130

busy. A circuit can now be traced from the winding of relay 478, conductor 484, bank contact 486, wiper 450, armature 461, armature 448 to grounded conductor 418. Wiper 449 will apply ground to bank contact 481, conductor 482, to armature 483, received from grounded conductor 418 by way of armatures 448 and 461. This would falsely ground conductor 477 were it not for the fact that armature 483 is now attracted so that conductor 477 will not constitute ground potential, depending upon whether the said chained armatures controlling relay 475 are all not closed. Under this condition the calling subscriber at 15 telephone T2 will perceive a special tone applied from grounded tone source T4 over conductor 487, bank contact 488, wiper 452, conductor 471, armature 470, conductor 322 and over the before traced path including 20 calling telephone T2 upper winding of relay 502 to grounded battery. The calling subscriber perceiving the tone will understand the condition set forth hereinbefore ensues, wherein a special tone from source T4 was 25 applied to wiper 406 of element B.

It was set forth hereinbefore how, upon relay 550 actuating, relay 401 de-actuated, to in turn cause relay 416 to de-actuate. It is manifest that were element C in a seized condition with relation to an accessible trunk, upon relay 401 de-actuating consequent to relay 550 actuating, relay 467 will de-actuate and thereby cause the seized trunk to be released subject to seizure otherwise. 30

Assuming a call from telephone T11 to telephone T7, the calling number of which is "21211" upon the calling subscriber at telephone T11 removing the receiver from the switchhook a circuit can be traced from the 35 winding of slow-releasing relay 850, contact 845, line conductor 851, through the telephone T11, line conductor 852, to grounded contact 846, relay 850 actuating. Assuming that private bank contact 853 does not constitute ground potential, indicating that first 40 selector O is idle, a circuit can be traced from the winding of motor magnet M11, armature 855, winding of relay 844, private conductor 855, to grounded armature 856, relay 844 actuating. Motor magnet M11 will not actuate with the winding of relay 844 included in series therewith. A circuit can now be traced, before relay 850 deactuates, from grounded armature 856, conductor 855, armature 857, conductor 858, wiper 859, bank contact 853, conductor 860 to the armature in first selector O corresponding to the armature in selector H co-operating with grounded contact 812. Armatures 862 and 863 complete the connection from the calling line conductors 851 and 852 to wipers 864 and 865, resting on bank contacts 866 and 867, which lead to conductors 868 and 869, respectively, and which extend to the windings of a relay 60 in selector O corresponding to relay 801 of selector H. So it is clear that ground is applied to conductor 860 from within selector O, before armature 856 retracts and, therefore, no ground lapse will occur to conductor 855 and to wiper 859 at this juncture. 70 Thus far the functioning of lineswitch M has been in accordance with lineswitches well known in the art. However, it will be assumed that bank contact 853 constitutes ground potential by reason of selector O having been seized by some other lineswitch and, therefore, a circuit can be traced from grounded contact 853, wiper 859, conductor 858, armature 857, armature 870, armature 855, winding of motor magnet M11 to 80 grounded battery, motor magnet M11 actuating, and upon its de-actuation advances the wipers 859, 864 and 865 one step into engagement with the next set of bank contacts leading to a selector belonging to the group containing selector O. If wiper 859 again encounters ground on bank contact 871 the same functioning will occur as last described wherein bank contact 853 constituted ground potential. This process will continue until 85 an ungrounded bank contact, indicating that a trunk to an idle selector belonging to the group containing selector O has been encountered, whereupon relay 844 will actuate under similar conditions to that described, 90 the trunk to the idle selector being thus seized. It is manifest that if all the selectors of the group accessible to lineswitch M are busy, and, therefore, all the bank contacts engageable by wiper 859 constitute ground 95 potential, the motor magnet M11 will continue to vibrate and drive the wipers 559, 564, and 565 continuously as long as relay 850 is actuated, which condition will ensue for 100 its period after the calling subscriber at telephone T11 replaces his receiver after finding that he cannot complete his call, perhaps after operating the calling device 872 in accordance with the telephone number of the line leading to telephone T7. 105

The present invention contemplates the novel function of applying a tone source T'11 audible to the calling subscriber during the period the lineswitch M is in the process of hunting for a trunk to an idle selector as 110 set forth and, therefore, the calling subscriber will know that it will be fruitless to start sending the impulses through the agency of his calling device 872 as long as he discerns this special tone after initiating the call as set forth. The tone can be traced from ground through armature 873, contact 845, armature 862, conductor 851, telephone T11, conductor 852, armature 863, to grounded contact 846. However, as soon as 115 relay 844 becomes actuated and its armature 862 is thus attracted, the said tonepath will be opened, the tone ceasing and therefore, indexing to the calling subscriber at telephone T11 that an idle selector has been seized by 120 125 130

his line terminating lineswitch M, and that the sending of control impulses may proceed normally.

The selector O having been seized, the first digit "2" will be sent through the agency of the calling device 872, whereupon selector O will be caused to function in the manner now well understood, and in view of the foregoing descriptions and the cited patents, and it will 10 select and seize a trunk leading to an idle selector N on its second bank level. Upon calling the second digit "1" the selector N will function in the manner generally similar to that of selector O and seize a trunk leading to an idle repeater I on its first level. A circuit can now be traced from upper winding of relay 101, make-before-break spring 102, conductor 103, conductor 104, bank contact 875, wiper 876, conductor 877, bank contact 20 879, wiper 880, conductor 869, bank contact 866, over the traced circuit path including telephone T11 to bank contact 867, conductor 868, wiper 881, bank contact 882, conductor 883, wiper 884, bank contact 885, conductor 886, conductor 105, make-before-break spring 106, to the lower winding of relay 101, relay 101 actuating.

A circuit can now be traced from the winding of slow-releasing relay 108 to grounded armature 109, relay 108 actuating. A circuit can now be traced from grounded contact 112 to armature 113 and contact 114 and to conductor 813. It will be recalled when conductor 813 is grounded, the repeater I is 30 guarded against intrusion by selector N (and selector P) on both the first and second levels of bank contacts accessible thereto. Contact 114 leads to conductor 115 and to the winding of slow-actuating relay 840, causing it to actuate. A circuit can now be traced from grounded battery through the upper winding of relay 603, make-before-break spring 604, upper winding of relay 605, armature 606, armature 607, conductor 629, armature 806, 40 conductor 841, armature 117, conductor 118, armature 119, conductor 120, outside winding of electro-polarized relay 125, make-before-break spring 126, upper winding of relay 127, conductor 128, armature 129, conductor 130, armature 804, conductor 805, armature 613, 50 armature 614, lower winding of relay 605, make-before-break spring 615, lower winding of relay 603 to ground, relay 605 actuating and relay 603 remaining normal, due to the neutralizing effect of its windings as hereinbefore set forth. A circuit can now be traced from grounded battery through the inside winding of relay 125 to grounded conductor 115. However, relay 125 is similar in 55 characteristics to relay 624, and therefore, relay 125 is not operatively energized. The direction of current traversing the outer winding traced tends to neutralize the tractive effort exerted by the electro-polarizing inner winding, but as will appear, the direction of cur-

rent in the outer winding is subject to reversal, under which condition it will energize cumulatively with the inner winding, and under that condition said relay 125 will operatively attract its armatures. 70

Consequent to relay 605 actuating, relay 617 actuates as hereinbefore set forth and ground is applied to conductor 427. Conductor 427 being grounded applies ground to conductor 426 and to the multiplied private 75 bank contacts as 407 and 442, of the duplex lineswitches having access normally to switch E, so that the seized trunk leading from selector N through repeater I is non-seizable from the sub-office by being thus 80 guarded.

At this juncture relay 844 of lineswitch M is maintained actuated from grounded contact 112, armature 113, conductor 813, bank contact 16, wiper 887, conductor 888, bank 85 contact 889, wiper 890, conductor 860, bank contact 853, wiper 859, conductor 858, armature 857, winding of relay 844, armature 855, winding of motor magnet M to grounded battery. Relays 127, 101 and 108 in repeater I 90 are actuated. Relay 840 in selector H is actuated. Relays 605 and 617 in switch E are actuated.

In the hereintofore description relating to switch E it functioned as an outgoing trunk 95 repeater in a manner generally the same as trunk repeater I functions, as will appear presently. However, in the descriptions about to be entered into the switch E will function as an incoming second-third selector 100 in the sub-office in a manner generally the same as the first selector H as set forth hereinbefore. So it will be clear, presently, how the switch E, which has been termed 105 a reciprocal-functioning switch hereinbefore, serves the novel purposes characterizing it.

With further reference to switch E, it has been hereinbefore stated that its wipers 641 and 644 have access to connectors F and G alternatively (in common with switch D) 110 through bank contacts on its second level, depending upon the numerical value of the digit sent effecting the seizure of the trunk, leading through repeater I, by selector N. The connectors F and G have been described 115 as belonging to the "2" hundred group of the "22" thousand and the "21" thousand subscribers' line groups of the exchange, respectively. It is manifest that were the connector F in the "23" thousand group as assumed with relation to the description with reference to switch D, the connections between switch D and switch E would be correlated by transferring the trunk conductors connected to bank contacts 17, 891, and 892 120 of the second level in connector N to the corresponding bank contacts 893, 894 and 895 respectively of the third level of bank contacts.

Under the condition of the second digit 125

sent being "2", it will appear presently, that the bank contacts leading to connector F and other connectors of its group are barred against seizure by switch E.

- 5 Upon the calling subscriber at telephone T11 manipulating the calling device 872 in accordance with the third digit "2", relay 101 will de-actuate and re-actuate two times responsive thereto, whereupon grounded armature 109 will apply its ground through armature 133 to the winding of slow-releasing relay 134, said relay 134 actuating. Armature 119 attracting, removes the outside winding of relay 125 from the traced path including it.
- 10 Armature 129 retracting opens the traced circuit (bearing in mind that the outside winding of relay 125 is excluded) including the windings of relay 605, therefore, relay 605 will in turn de-actuate and re-actuate two times. Upon the retraction of grounded armature 616 a circuit can be traced from said grounded armature, armature 630, armature 631, conductor 632, armature 633, winding of slow-releasing relay 650 to the winding of vertical magnet V6. Vertical magnet V6 will, therefore, operate two times and step the shaft carrying wipers 641 to 644 two vertical steps, into alignment with the second level of bank contacts. Upon relay 650 actuating incidental to the first impulse to the vertical magnet V6, ground from conductor 427 will be applied through armature 651, conductor 652, off-normal spring 653 to the winding of shunted relay 654 causing it to
- 25 actuate. A locking circuit to ground is closed from the winding of said relay 654, spring 653, conductor 652, armature 655 on rotary magnet R6, armature 656 to grounded contact 657. At the termination of the period of relay 650 following the last (second) impulse to the vertical magnet V6, whereupon armature 651 will retract, a circuit can be traced from grounded conductor 427, armature 651, armature 658 to the winding of the rotary magnet R6, causing it to advance wipers 641 to 644 one vertical step into engagement with bank contacts 661 to 654, and to incidentally open the locking circuit of relay 654, causing it to de-actuate. If wiper 641, or its tied wiper 642, encounters ground potential on either or both bank contacts 661 and 662 a circuit path will be closed from the winding of relay 654, spring 653, conductor 652, armature 655, conductor 665, armature 666, conductor 667, wiper 641 (or wiper 642) to bank contact 661 (or 662), causing relay 654 to reactuate and re-establish the path from grounded conductor 427, armature 651, armature 658 to the winding of rotary magnet R6, causing it to refunction as before and advance the wipers 641 to 644 into engagement with bank contacts 668 to 671 and unlock the circuit energizing relay 654 at armature 655, as before described. It is manifest
- 30 that this cycle of operations will re-occur as

long as wiper 641 (or 642) encounters ground potential, regardless of the state of bank contacts engaged by wiper 642. It is now clear that when wipers 641 to 644 engage bank contacts 661 to 664 ground from conductor 427 through armature 676 will be applied over conductor 677, bank contact 661, wiper 641, conductor 667, armature 666, conductor 665, armature 655, conductor 652, spring 653 to the winding of relay 654, causing it to actuate and lock to grounded contact 657 and close the energizing circuit to rotary magnet R6 through armature 658 and 651 to grounded conductor 427, to advance the wipers 641 to 644 a rotary step into engagement with the bank contacts 668 to 671 respectively. Bank contact 668 being in multiple with bank contact 661 it will also constitute ground potential, whereupon the wipers 641 and 644 will be advanced a further rotary step, this cycle of operations continuing until neither wiper 641 or 642 encounters ground potential.

It will be assumed that bank contact 661 constituted ground potential when first engaged by wiper 641. Under this condition a short circuit to ground would be applied from conductor 665, armature 666, conductor 667, wiper 641, bank contact 661, conductor 677, armature 676 to conductor 427. So upon the retraction of armature 655, relay 654 will be re-energized and actuate over the circuit path including spring 653, conductor 652, armature 655, conductor 665 armature 666, conductor 667, wiper 641, bank contact 661, conductor 677, armature 676, to conductor 427. Relay 654 will be held actuated over a locking circuit established through armature 655 to grounded contact 657 as before set forth, and the energizing circuit of rotary magnet R6 will be re-established through armature 658, armature 651 to grounded conductor 427, whereupon wipers 641 to 644 will be driven an additional rotary step into engagement with bank contacts 668 to 671 respectively. Bank contact 668 constituting ground potential (being in multiple with bank contact 661), the cycle of operations which ensued consequent to wiper 641 engaging bank contact 661 will be repeated, the wipers 641 to 644 being rotated into engagement with bank contacts 672 to 675 respectively. Connector G being assumed to be disengaged, and therefore, conductor 704 is free of ground potential, and that bank contact 672 leading to conductor 678 is open, armature 676 being retracted, neither wiper 641 nor 642 will encounter ground potential, and therefore, ground potential will be removed from conductor 665 (formerly applied by way of armature 666 and conductor 667), the winding of relay 680 will be included between grounded conductor 427, conductor 665, armature 655, conductor 652, spring 653 to the winding of relay 654. The characteristic of

125

130

relay 654 is such that it will not operatively energize, included in the circuit with the winding of relay 680, but 680 will operatively energize under the latter condition. Therefore, relay 680 will actuate, and relay 654 will de-actuate upon ground potential being removed from conductor 667 upon wipers 641 to 644 being rotated into engagement with bank contacts 672 to 675 respectively.

The telephonic circuit traced to conductors 104 and 886 can now be traced from conductor 104, condenser 136, conductor 137, armature 119 (relay 134 having retracted its period after the second impulse was applied by armature 109) conductor 118, armature 117, conductor 841, armature 806, conductor 629, armature 607, armature 606, conductor 683, wiper 643, bank contact 674, conductor 702, to the upper winding of relay in connector G corresponding to 701 in connector F. And from the lower winding of the said relay in connector G, conductor 587, bank contact 675, wiper 644, conductor 684, armature 614, armature 613, conductor 805, armature 804, conductor 130, armature 129, conductor 128, condenser 138, to conductor 886. The relay in connector G corresponding to 701 will be maintained actuated over the described circuit up to conductors 137 and 128, and from conductor 128 through the upper winding of relay 127 make-before-break spring 126, outer winding of relay 125 to conductor 137. Bearing in mind that relay 125 is similar in characteristics to relay 624 and the fact that the current traversing the outer winding of relay 125 energizes in opposition to the inner electro-polarizing winding thereof, it will appear that its armatures will remain normal at this juncture.

It has been set forth hereinbefore how conductor 704 became grounded following the seizure of connector G wherein its line relay corresponding to 701 is caused to actuate and, therefore, bank contact 673 will be caused to constitute ground potential following the actuation of relay 680. Wiper 642 being in engagement with bank contact 673 communicates this ground over conductor 667, armature 666, to conductor 427 before the period of relay 617 has expired following the disassociation of the windings of relay 605 and, therefore, before armature 602 has retracted. So that no lapse of ground potential occurs to conductor 427 and, therefore, the energizing circuit of relay 680 is maintained, it being the only relay in switch E now actuated.

Upon the calling subscriber at telephone T11 sending the last two digits "11" of the called telephone line leading to telephone T7 the relay 101 in repeater I will operate correspondingly, and control its dependent relay in connector G corresponding to relay 701, whereupon the connector G will function in a manner as hereinbefore specifically set forth in the assumed call from telephone T2 to the

said telephone T7. Upon the response of the called party at telephone T7, the direction of current projected from connector G over conductors 702 and 587 will be reversed and consequently the outer winding of relay 125 will now energize its core cumulatively with the inner winding thereof, under which condition it will operatively attract its armatures. A circuit can now be traced from grounded contact 141, conductor 142, to the winding of relay 143, causing it to actuate and reciprocate the relation between the windings of relay 101 and conductors 104 and 886, therefore, reversing the direction of current traversing the circuit including the receiver of the calling telephone T11. The purpose of this reversal has been referred to hereinbefore and has no operative object in the assumed call.

The lower armature of relay 143 is attracted into engagement with make-before-break spring 126, whereupon the upper and lower windings of relay 127 are included in series relation with the outer winding of relay 125 and in bridge of conductors 841 and 130.

Assuming that after the telephonic connection has been completely established between the telephone T11 and telephone T7 the called subscriber at telephone T7 replaces the receiver, followed by the calling subscriber at telephone T11 replacing the receiver. Relay 101 will retract followed by relay 108 its period thereafter. This will remove the guarding potential described as applied over conductor 813. Relay 840 will retract dependent upon relay 108. The relay in connector G corresponding with 701 will be de-energized due to the retraction of armature 129, and the now incidental fact that the windings of relay 801 (due to the retraction of relay 840), are connected in series with the windings of the said relay corresponding to 701, with battery, at opposite ends, and also ground, opposing, so that ground is removed from conductor 704 upon the retraction of relay in connector G corresponding to 703, whereupon the energizing circuit for relay 680 is opened and it retracts. A circuit can now be traced from grounded armature 616, armature 630, armature 631, spring 685 to the winding of release magnet Re6, the said release magnet actuating and restores the wipers 641 to 644 to normal position. The connector G restores to normal position as hereinbefore described. Ground potential being removed from conductor 813 selectors N and O will be restored in the well known manner and, ground being removed from conductor 860 consequent to the restoration of selector O, relay 844 will de-actuate. The circuits concerned in the assumed call from telephone T11 to telephone T7 are now normal.

Assuming a call from telephone T11 to

telephone T7' the calling number of which is "22212". Upon the calling subscriber at telephone T11 removing the receiver from the switchhook selector O will be seized as hereinbefore set forth. Upon the calling subscriber at telephone T11 manipulating the calling device 872 in accordance with the first digit "2" the selector O will function as before set forth and seize selector N.

5 10 Upon the calling subscriber at telephone T11 manipulating the calling device 872 in accordance with the second digit "2" selector N will function as before described when digit "1" was sent, only in this instance its 15 wipers will rotate-in on the second level and seize the first disengaged trunk, which will be assumed to be the one leading from the first set of bank contacts 17, 891 and 892 including trunk repeater I as before. However, it is borne in mind that a different set 20 of leading-in telephonic conductors 896 and 897 are seized, private conductor 813 being common to the first bank contacts 16 and 17 of both the first and the second levels.

25 It will also be noted that conductors 886 and 897 are joined, so that bank contacts 885 and 892 are common to the same telephonic conductor. A circuit can now be traced from the upper winding of relay 101, spring 102, 30 conductor 103, conductor 144, winding of relay 145, conductor 896, bank contact 891, wiper 876, over the before-traced path including telephone T11 to wiper 884, bank contact 892, conductor 897, conductor 886, spring 106, to the lower winding of relay 101, relays 35 101 and 145 actuating. Grounded armature 109 attracting causes relay 108 to actuate for the objects before described, including the further object of closing the circuit to the 40 winding of relay 840. Relay 145 being energized coincidentally with relay 101 will attract its armature 146 before relay 840 will attract its armature 898, due to the slow-actuating characteristics of relay 840, and because it operates in a secondary circuit to 45 relay 101. Relay 840, upon attracting its armature 898, will short circuit the winding of relay 145, causing it to retract, but due to the short-circuit condition armature 146 will remain in engagement on the co-operating 50 grounded contact an appreciable period. It is thus manifest that under the condition of the selector N seizing trunk repeater I through the second level of bank contacts, relay 145 will be caused to actuate and apply a ground to conductor 805 for an appreciable period after the seizure, whereupon the ground is removed and a short 55 circuit placed between conductor 896 and 144 by means of armature 898, so that the circuits are now essentially as if the trunk including the repeater I had been seized (as before described) through the first level of 60 bank contacts accessible to selector N in lieu 65

of the second level of bank contacts accessible to selector N.

Relay 605 and its dependent relay 617 will function as hereinbefore set forth when subscriber at telephone T11 was assumed to call 70 telephone T7. However, there is an important difference in the functioning of switch E under the condition of the present assumed call to telephone T7' than under the condition of calling telephone T7. It has been stated hereinbefore that the windings on relay 603 oppose each other and, therefore, exert no tractive effect on its armatures when currents traverse both its windings included serially with the windings of relay 605. It will now appear that at the time ground was applied to conductor 805 by armature 146 that the return path for the current traced as emanating from grounded battery through the upper windings of relays 80 604 and 605 in series, is short-circuited to ground by way of armature 146 and, therefore, does not permit to return current to traverse the lower windings of relay 605 and 603 in series for the time armature 146 is attracted. Under this condition it is manifest that the lower winding of relay 603 cannot neutralize the tractive effect produced by the energization of the upper winding thereof, and, as a consequent, its armatures will be 95 operatively attracted, it being borne in mind in this connection that the current traversing the upper windings of relays 603 and 605 is of sufficient strength to operatively affect both relays 603 and 605. 100

Upon the actuation of relay 603 its armatures 686, and 687 will apply grounded battery and ground to the upper and lower windings of relay 605 respectively and dis-associate the windings of relay 603 from the 105 windings of relay 605 at make-before-break springs 604 and 615, so that the windings of relay 603 are excluded from the traced circuit including armature 129 of repeater I, without interrupting the energization of relay 605, and it will also appear that a locking circuit is established from grounded battery through the upper winding of relay 605, armature 688, armature 689, to the grounded conductor 427. 110

115 Armature 676 is now applying ground from conductor 427 to conductor 678 and to bank contact 672 and its multiples including 690. Conductor 677, leading from bank contacts 661 and 668 is free, and therefore, the said 120 661 and 668 do not constitute ground potential, but that bank contacts 672 and 690 do constitute ground potential. It is clear now that whether bank contacts 661 and 662 which refer to connector F and other connectors of its group, or whether bank contacts 672 and 690 referring to connector G and other connectors of its group, shall constitute ground potential, which in view of the descriptions 125 will bar the switch E against seizing a set of 130

bank contacts in which there is a companion bank contact engageable by wiper 641 that constitutes ground potential, and in view of the fact that connector F belongs to the "22" 5 thousand group of subscribers' lines, and the connector G belongs to the "21" thousand group of subscribers' line, the set-up condition in switch E, brought about by the actuation of relay 603 resultant to digit "2" being sent as the second digit, in lieu of the digit "1", will definitely determine in what thousand group a connector can be seized by the switch E.

In this connection attention is directed to 15 the fact that conductors 677 and 678 are local to the switch E and have no relation to other switches of its group, and that the relationship of the bank contacts tied to the conductors 677 and 678 would be carried out in 20 switch E to correspond with the tieing of bank contacts in switch D to conductors 556 and 566 which have been clearly set forth hereinbefore.

Upon the calling subscriber at telephone 25 T11 manipulating the calling device 872 in accordance with the third digit "2", relay 101 will de-actuate and re-actuate two times responsive thereto, as in the previous descriptions, and other functions in repeater I will 30 be effective as hereinbefore described when the third digit "2" was sent. Also, switch E will function correspondingly as before described and rotate-in on the second level and hunt for an idle connector, or pass over contacts engaged by wiper 641 that may constitute ground potential. Remembering that bank contacts 661 and 668 do not now constitute ground potential by reason of the attracted condition of armature 676 there will 40 be no false busy condition applied which will bar the switch E from selecting connector F or other connectors of its group, provided they are not actually busy. Assuming that connector F is idle, upon wipers 641 to 644

45 engaging bank contacts 661 to 664 respectively, when armature 656 retracts from its grounded contact 657, the ground short circuit condition applied to the upper winding terminal of relay 680 is removed and it will 50 actuate as before described under this condition, completing the hereinbefore described telephonic circuit from telephone T11 (bearing in mind the stated relation of the outside winding of relay 125 to conductors 841 and 55 130) to the windings of relay 701, relay 701 actuating and causing conductor 501' to become grounded in the manner as before clearly set forth. The ground from conductor 501' will be applied to bank contact 662, wiper 642, 60 conductor 667, armature 666, to conductor 427 before relay 617 de-actuates consequent to the armatures 606 and 614 disassociating the windings of relay 605. So that no lapse of ground potential will occur to conductor 427, 65 and the energizing circuit including the wind-

ing of relay 680 will therefore be maintained dependent upon relay 701, which latter is controlled from the switchhook of calling telephone T11 through the agency of armature 129 on relay 101. Conductors 677 and 678 (and also 556 and 566 of switch D) are common to the respective alternative false-busy contacts engageable by wiper 641 (and 521) of all the levels co-operative to switch E (and D).

Upon the actuation of relay 680 as set forth, the locking circuit of relay 603 is opened at armature 689, as the discriminating ground applied through armature 676 has no function after the seizure of switch E, involved in the actuation of relay 680. At this juncture conductor 677 leading to bank contacts 661 and 668 is re-applied to grounded conductor 427. However, upon the release of switch E, occurring because of 85 the completion of the traced circuit including the winding of the release magnet Re6, as before described upon the energizing circuit including the winding of relay 680 becoming opened consequent to the calling subscriber replacing the receiver and thereby causing the de-actuation of relay 101, followed by relays 701 and 703 in sequence, ground potential is removed from conductor 501, conductor 427 and bank contacts 661 and 668.

Going back to the condition last described wherein switch E has seized connector F, it will next be assumed that the calling subscriber at telephone T11 manipulates the calling device 872 in accordance with the last two digits "12" of the number of the called telephone T7' whereupon the connector F will function as before clearly set forth, and seize and signal upon the line leading to telephone T7'. Upon the called subscriber at telephone T7' responding, relay 125 will be operatively energized as before described and referred to in relation to connector G, and the current traversing the receiver at calling telephone T11 will be reversed to that initially established to it, for reasons set forth hereinbefore. Upon the subscriber at telephone T7' replacing his receiver and the subscriber at telephone T11 replacing his receiver the switches and circuits concerned in the assumed call from telephone T11 to telephone T7' will restore to the normal condition as hereinbefore set forth with relation to the call from telephone T11 to telephone T7.

It is manifest that had the calling subscriber at telephone T11 directed the call to telephone T2, the telephone number of which is "22211" the functioning of all the switches concerned in the described call from telephone T11 to telephone T7' would be the same as described in relation thereto, only that the wipers 745 and 747 of connector F would have been stepped into engagement 120

with the first set of bank contacts 781 to 783 in lieu of the second set 751 to 753. Under this condition conductor 315 would have ground applied to it by way of sideswitch 5 wiper 743, wiper 745 and bank contact 781, whereupon relay 314 would be partially actuated, that is, so that armatures 302 and 305 would disengage the resting contacts, but not engage their make contacts, due to a mechanical interlocking means co-operative between relays 314 and 301 which incapacitates relay 314 against complete actuation if relay 301 has its armatures in normal position. Under this condition there are no affecting attachments to the telephonic conductors 330 and 331.

Assuming a call from telephone T12 to telephone T7. Upon the calling subscriber at telephone T12 removing the receiver line-switch R will function in a manner similar to lineswitch A hereinbefore described and seize first selector Q. Upon the first digit "2" of the called number being sent wipers 151 to 153 will seize the trunk leading to selector P from the first set of bank contacts of its second level in the manner as hereinbefore set forth. Upon the second digit "1" being sent selector P will function in the manner as hereinbefore described with reference to selector N, wipers 154 to 156 seizing the first set of bank contacts of the first level leading to conductors 18, 157 and 158 attaching to conductors 813, 886 and 104 respectively, leading to trunk repeater I. The sending of the last three digits "211" will cause trunk repeater I, selector H, switch E and connector G to function as before when telephone T7 was assumed called from telephone T11. Had the last assumed call been directed to telephone T7' in lieu of telephone T7 wherein the second digit is "2" in lieu of the "1" last assumed, selector P would rotate-in on its second level and its wipers would seize the first set of bank contacts thereon leading to conductors 18, 159 and 160 attaching to conductors 813, 897, and 896 respectively, leading to trunk repeater I. The sending of the last three digits "212" will cause trunk repeater I, selector H, switch E, and connector F to function as before when telephone T7' was assumed called from telephone T11. It will be noted in this connection that first selector "Q" is located in the "3" main-branch office and that selector N is in the "2" main-branch office and, further, that selector P is an incoming second selector in the "2" main-branch office having its co-operating bank contacts in multiple relation with the corresponding bank contacts co-operating with selector N.

Bank contacts 801', 802', 803' is the first set of bank contacts of the third level accessible to selector H, located in the "2" main-branch office, and lead to incoming second selector S in the "8" main-branch office. Se-

lector S has access to bank contacts leading to local second selector T, which has access to connector U, which latter has access to telephone T12 located in the "8" main-branch office district.

Referring to Fig. 1, first selector O has access through its third level over a group of trunks one of which is b, leading to an incoming second selector S' in the "3" main-branch office which has common access with incoming second selector S to local second selector T, so that calls from telephone T11 for example, can be extended by way of first selector O, trunk b, incoming second selector S' third selector T, connector U to telephone T12. Also, incoming second selector P has access through its third level over a group of trunks, one of which is a, to local third selector K. Third selector K is also commonly accessible from second selector J, so that calls from telephone T12, for example, can be extended by way of first selector Q, incoming second selector P, third selector K, connector L, to telephone T11.

Referring further to Fig. 1 a selector Y is shown introduced into the trunk extending to connector F. Also selector Z is shown introduced into the trunk extending to connector G. These selectors Y and Z are similar to K, for example. Under this condition if the trunk leading to connector F from the bank contacts of switches D and E, in common, lead to selector Y and the first set of bank contacts of the second bank level of selector Y lead to connector F it will be manifest that in calling telephone T7' for example, it will be necessary to introduce an extra digit, the telephone number being "222212". That is, an extra digit "2" effective to selector Y, is introduced before the last two digits, (which latter are effective to the connector F), are sent. In the same manner the introduction of the selector Z will entail calling telephone number "212211" in reaching telephone T7. That is, an extra digit "2" is introduced before the last two digits, (which latter are effective to the connector G), are sent.

It follows from the foregoing that since selectors Y and Z can have ten bank levels, for example, and that these can all be extended to connector groups corresponding to the groups containing connectors F and G that the accessibility of the switches D and G, through their multiplied bank contacts on the second level will be expanded or amplified ten times and, therefore, two thousand subscribers' lines will be accessible from the second bank level accessible to each switch D and E or that twenty thousand subscribers' lines will be accessible if, for example, switches D and E have common access to ten levels disposed similarly to the second level shown in the drawings.

Under the last above method of connection,

the sub-exchange would have a capacity of twenty thousand lines, but telephone numbers therein will have six digits instead of five digits as used in calling the telephones directly related to a main-branch exchange office.

It is manifest that the alternative selecting in the bank levels accessible to the switches D and E may be omitted without departing from the scope of the present invention. That is, to say, for example, that there would be no "22" thousand group in the sub-office and that the repeater I would be accessible only from the first levels of selectors N and P. The "22" thousand group of lines could then be reserved for direct connection with the "2" main-branch office, or could comprehend telephone numbers in a separate sub-office located in the same building; for example, with the "21" thousand sub-office, or at some remote district of the exchange, sub-ordinate to the "2" main-branch office. Under this condition conductors 556, 566, 677 and 678 and the attached bank contacts would be dispensed with, together with the circuits and equipments in the switches D and E co-operative with the said conductors 556, 566, 677 and 678. Under this condition connectors in the group containing G would not be installed, the entire second level accessible to switches D and E being accessible to a single group of connectors containing connector F as a first choice, and would be the "2" hundred group of connectors of the "21" thousand group of subscribers' lines.

Other modifications may be made by way of amplifying the system described by way of example, or by curtailing it, without departing from the scope of the invention in view of the subjoined claims.

I claim:—

1. An automatic switch which will primarily rotate its wipers on its normal level responsive to directive control, means for releasing the wipers to normal position responsive to predetermined directive control after rotating, means for again rotating the wipers responsive to a second application of directive control, means responsive to predetermined directive control involved in the said second application for again releasing the wipers and for adapting the switch to then step the wipers vertically.

2. An automatic switch which will primarily rotate its wipers on its normal level responsive to directive control, means for releasing the wipers to normal position responsive to predetermined directive control after rotating, means for again rotating the wipers responsive to a second application of directive control, means responsive to predetermined directive control involved in the said second application for again releasing the wipers and for adapting the switch to

then step the wipers vertically responsive to a third application of directive control.

3. An automatic switch which will primarily rotate its wipers on its normal level responsive to directive control, means for releasing the wipers to normal position responsive to predetermined directive control after rotating, means for again rotating the wipers responsive to a second application of directive control, means responsive to predetermined directive control involved in the said second application for again releasing the wipers and for adapting the switch to then step the wipers vertically responsive to a third application of directive control and for thereafter rotating.

4. An automatic switch which will primarily rotate its wipers on its normal level responsive to directive control, means for releasing the wipers to normal position responsive to predetermined directive control after rotating, means for again rotating the wipers responsive to a second application of directive control, means responsive to predetermined directive control involved in the said second application for again releasing the wipers and for adapting the switch to then step the wipers vertically responsive to a third application of directive control and for thereafter rotating automatically as a selector.

5. An automatic switch which will primarily rotate its wipers on its normal level responsive to directive control, means for releasing the wipers to normal position responsive to predetermined directive control after rotating, means for again rotating the wipers responsive to a second application of directive control, and means for incapacitating the switch against directive control if the said second application of directive control is not predetermined.

6. In a telephone system a calling line, a connected dual functioning switch therefor which will function to negate a progressed call from the calling line responsive to predetermined normal calling control and as a linking switch thereafter, two groups of switches accessible to the dual functioning switch, means on the calling line for directly controlling the operation of the dual functioning switch, means responsive to predetermined directive control for rendering the dual functioning switch incapacitated against the directive control means, and means differently responsive to predetermined directive control for adapting the switch to thereafter function as a linking switch responsive to the directive control means wherein one or the other of the said two groups of switches will be accessible and the alternative group barred depending upon the predetermined directive control which adapted the switch to function as a linking switch.

7. In a telephone system a calling line, a

connected dual functioning switch therefor which will function to negate a progressed call from the calling line responsive to predetermined normal calling control and as a linking switch thereafter, two groups of switches accessible to the dual functioning switch, means on the calling line for directly controlling the operation of the dual functioning switch, means responsive to predetermined directive control for rendering the dual functioning switch incapacitated against the directive control means, and means differently responsive to predetermined directive control for adapting the switch to thereafter function as a linking switch responsive to the directive control means wherein one or the other of the said two groups of switches will be accessible depending upon the predetermined directive control which adapted the switch to function as a linking switch.

8. In a telephone system a calling line, a connected dual functioning switch therefor which will function to negate a progressed call from the calling line responsive to predetermined normal calling control and as a linking switch thereafter, two groups of switches accessible to the dual functioning switch, means on the calling line for directly controlling the operation of the dual functioning switch, and means differently responsive to predetermined directive control for adapting the switch to thereafter function as a linking switch responsive to the directive control means wherein one or the other of the said two groups of switches will be accessible depending upon the predetermined directive control which adapted the switch to function as a linking switch.

9. In a telephone system a calling line, a connected dual functioning switch therefor which will function to negate a progressed call from the calling line responsive to predetermined normal calling control and as a linking switch thereafter, two groups of switches, means on the calling line to directly control the operation of the said dual functioning switch responsive to directive control differently applied for thereupon adapting it to function as a linking switch responsive to directive control, and means differently responsive to the said differently applied control wherein one or the other of the said two groups of switches will be accessible and the alternate group barred depending upon the predetermined directive control which adapted the dual functioning switch to function as a linking switch.

10. In a telephone system a calling line, a connected dual functioning switch therefor which will function to negate a progressed call from the calling line responsive to predetermined normal calling control and as a linking switch thereafter, two groups of switches, means on the calling line to directly

tively control the operation of the said dual functioning switch responsive to directive control differently applied for thereupon adapting it to function as a linking switch responsive to directive control, and means differently responsive to the said differently applied control wherein one or the other of the said two groups of switches will be accessible depending upon the predetermined directive control which adapted the dual functioning switch to function as a linking switch.

11. In a telephone system, the combination with an automatic switch having a movement in two planes, bank contacts for said switch divided into a plurality of levels, trunk lines terminating in said bank contacts, the bank contacts in each level being divided into a plurality of groups, of means for operating said switch in one plane to select a group of bank contacts in one of said levels, and means for operating said switch in the other plane to select a particular level of bank contacts.

12. In a telephone system, the combination with an automatic switch having a movement in two planes, bank contacts for said switch divided into a plurality of levels, and trunk lines terminating in connector switches leading from said bank contacts, said connector switches being divided into groups and sub-groups, of means for operating said switch in one plane to select a particular group of said connector switches, and means for operating said switch in the other of said planes to select a particular sub-group.

13. In a telephone system, the combination with an automatic switch having a movement in two planes, bank contacts for said switch divided into a plurality of levels, trunk lines terminating in connector switches leading from said bank contacts, said connector switches being divided into groups and sub-groups, of means for operating said switch in one plane to select a particular group of said connector switches, means for releasing said switch, and means for operating said switch in the other of said planes to select a particular sub-group.

14. In a telephone system, the combination with an automatic switch having a movement in two planes, bank contacts for said switch divided into a plurality of levels, trunk lines terminating in connector switches leading from said bank contacts, said connector switches being divided into groups and sub-groups, of means for operating said switch in one of said planes to preselect one of said groups, and means for operating said switch in the other of said planes for selecting a particular sub-group in said preselected group.

15. In a telephone system, the combination with an automatic switch having a movement in two planes, bank contacts for said switch divided into a plurality of levels, trunk lines terminating in connector switches leading

from said bank contacts, said connector switches being divided into groups and sub-groups, of means for operating said switch in one of said planes to determine one of said groups, and means for operating said switch in the other of said planes to simultaneously select the predetermined group and a particular sub-group in said group.

16. In a telephone system, the combination with an automatic switch having a movement in two planes, bank contacts for said switch divided into a plurality of levels, trunk lines terminating in connector switches leading from said bank contacts, said connector switches being divided into groups and sub-groups of means for operating said switch in one of said planes to determine one of said groups, means for operating said switch in the other of said planes to simultaneously select the predetermined group and a particular sub-group in said group, and automatic means for operating said switch in the first-mentioned plane to select a particular connector in the selected sub-group.

25 17. In a telephone system, the combination with an automatic switch having a movement in two planes, bank contacts for said switch divided into a plurality of levels, trunk lines terminating in connector switches leading from said bank contacts, said connector switches being divided into groups and sub-groups, of means for operating said switch in both of said planes, and means controlled by said operation for selecting a particular one of said groups and a sub-group of said group.

18. In a telephone system, the combination with an automatic switch having a movement in two planes, bank contacts for said switch divided into a plurality of levels, trunk lines terminating in connector switches leading from said bank contacts, said connector switches being divided into groups and sub-groups, of means for operating said switch in both said planes, and means controlled by said operation for selecting a particular group, a particular sub-group and a particular connector in said sub-group.

19. In a telephone system, the combination with an automatic switch having a movement in two planes, bank contacts for said switch divided into a plurality of levels, trunk lines terminating in connector switches leading from said bank contacts, said connector switches being divided into groups and sub-groups, of means for operating said switch in one of said planes, means for releasing said switch, means for operating said switch in the other of said planes, means for again operating said switch in the first-mentioned plane, and means responsive to all of the said operations for selecting a particular one of said groups, a sub-group in said group and a particular connector in said sub-group.

20. In a telephone system, the combination

with an automatic switch having a movement in two planes, bank contacts for said switch divided into a plurality of levels, trunk lines terminating in connector switches leading from said bank contacts, said connector switches being divided into groups and sub-groups, of means for operating said switch in one of said planes, means for releasing said switch, means for operating said switch, and means operative as a result of said operations for selecting a particular group and sub-group of said connectors.

21. In a telephone system, the combination with an automatic switch having a movement in two planes, bank contacts for said switch divided into a plurality of levels, trunk lines terminating in connector switches leading from said bank contacts, said connector switches being divided into groups and sub-groups, of means for operating said switch in one of said planes to apply a busy potential to certain bank contacts in one of said levels, means for operating said switch in the other of said planes to select a particular level of bank contacts, and automatic means for causing said switch to hunt for a non-busy set of bank contacts in said level.

22. In a telephone system, the combination with an automatic switch having a movement in two planes, bank contacts for said switch divided into a plurality of levels, trunk lines terminating in connector switches leading from said bank contacts, said connector switches being divided into groups and sub-groups, of directly controlled means for operating said switch in one of said planes to apply a busy potential to certain bank contacts in all of said levels, means for operating said switch in the other of said planes to select a particular level, and automatic means for causing said switch to hunt for an idle set of bank contacts in the selected level.

23. In a telephone system, the combination with an automatic switch having movement in two planes, bank contacts divided into levels accessible to said switch, trunk lines leading to connector switches terminating in said bank contacts, said connector switches being divided into a plurality of groups in accordance with the levels in said switch and being subdivided into two main groups, the bank contacts in each level being correspondingly divided into two groups, of means for operating said switch in one of the planes to select one of said main groups, and means for operating said switch in the other of said planes to select one of said sub-groups.

24. In a telephone system, the combination with an automatic switch having movement in two planes, bank contacts divided into levels accessible to said switch, trunk lines leading to connector switches terminating in said bank contacts, said connector switches being divided into a plurality of groups in accordance with the levels in said switch and being

70

- subdivided into two main groups, the bank contacts in each level being correspondingly divided into two groups, of directly controlled means for operating said switch in one of said planes to predetermine one of said main groups and directly controlled means for operating said switch in the other of said planes to select the predetermined group. 5
25. In a telephone system, the combination with an automatic switch having a movement in two planes, trunk lines divided into groups and sub-groups accessible to said switch, of directly controlled means for operating said switch in one of said planes, means for releasing said switch, directly controlled means for reoperating said switch in the same plane, and means controlled by said operations for preselecting one of said groups. 10
26. In a telephone system, the combination with an automatic switch having a movement in two planes, trunk lines divided into groups and sub-groups accessible to said switch, of directly controlled means for operating said switch in one of said planes, means for releasing said switch, directly controlled means for reoperating said switch in the same plane, means controlled by said operations for pre-selecting one of said groups, and 15 directly controlled means for operating said switch in the other of said planes to select simultaneously the predetermined group and a particular sub-group therein. 20
27. In a telephone system, the combination with an automatic switch having a movement in two planes, trunk lines accessible to said switch, said trunk lines being divided into groups and sub-groups, and of directly controlled means for operating said switch in one plane to simultaneously select a particular group and sub-group. 30
28. In a telephone system, the combination with an automatic switch having a movement in two planes, trunk lines accessible to said switch, said trunk lines being divided into groups and sub-groups, of directly controlled means for operating said switch in one plane to simultaneously select a particular group and sub-group, and automatic 40 means for operating said switch in the other said planes to select a particular trunk line in the selected sub-group. 50
29. In a telephone system, the combination with first, second and third selectors and connectors, a telephone line, an automatic switch, means for connecting said line to said switch and to one of said first selectors, means controlled from said telephone line for simultaneously operating said automatic switch and said selector switch, means controlled by said first selector switch to extend said telephone line to one of said second selector switches, automatic means for releasing said automatic switch, means controlled from said telephone line for operating said second se- 60
- lector to extend the connection to one of said third selectors and for reoperating and releasing said automatic switch, means controlled by the operation of said automatic switch for releasing the connection to said first, second and third selectors, and means for thereafter operating said automatic switch, the operation of said automatic switch functioning as a combined second and third selector. 70
30. In a telephone system, the combination with an automatic switch having a movement in two planes, of connector switches divided into groups and sub-groups accessible to said switch, a relay in said switch for selecting one of said groups, and means for operating said switch in one of said planes to energize said relay. 75
31. In a telephone system, the combination with an automatic switch, bank contacts accessible to said switch divided into levels, connector switches divided into groups, trunk lines extending from said connectors to said bank contacts, means for operating said switch to select a particular level, trunk lines in said level extending to two of said groups, and automatic means in said switch to prevent connection with trunk lines in one of said groups. 85
32. In a telephone system, the combination with an automatic switch, bank contacts accessible to said switch divided into levels, connector switches divided into groups, trunk lines extending from said connectors to said bank contacts, means for operating said switch to select a particular level, trunk lines in said level extending to two of said groups, and determining means in said switch for preselecting in which group of trunk lines a trunk can be selected, and means for operating said switch to select a trunk in the predetermined group. 95
33. In a telephone system, the combination with an automatic switch, a plurality of groups of connector switches, bank contacts in said switch divided into a plurality of levels less in number than the number of groups of connectors, a set of wipers for said switch, and means in said switch for operating said wipers to connect with a connector in any one of said groups responsive to a single directed movement of the said switch. 100
34. In a telephone system, the combination with an automatic switch, a plurality of groups of connector switches, bank contacts in said switch divided into a plurality of levels less in number than the number of groups of connectors, a set of wipers for said switch, and means for operating said wipers to connect with a connector in any one of said groups responsive to effecting a single directed movement of the said switch. 110
35. In a telephone system, the combination with an automatic switch, a plurality of groups of connector switches, bank contacts 115

in said switch divided into a plurality of levels less in number than the number of groups of connectors, a set of wipers for said switch, and means for operating said 5 wipers to connect with a connector in any one of said groups responsive to a corresponding single directed movement of the wipers of the said switch.

36. In a telephone system, the combination 10 with an automatic switch, a trunk line terminating in said switch, trunk lines divided into groups and sub-groups commonly accessible to a set of wipers of said switch, of two paths over which the first-mentioned 15 trunk line may be seized, means for seizing said trunk line over one of said paths, and means controlled by such seizure for rendering one of said groups inaccessible to the 20 said set of wipers of said first-mentioned switch.

37. In a telephone system, the combination 25 with an automatic switch, a trunk line terminating in said switch, trunk lines divided into groups and sub-groups commonly accessible to a set of wipers cooperative with the said groups and sub-groups, of two paths over which the first-mentioned trunk line may be seized, means for seizing said trunk line over one of said paths, and means controlled by such seizure for rendering one of 30 said groups inaccessible to the said set of wipers of said first-mentioned switch.

38. In a telephone system, the combination 35 with an automatic switch, a trunk line terminating in said switch, trunk lines divided into groups and sub-groups commonly accessible to a set of wipers of said switch, of a plurality of paths over which the first-mentioned trunk line may be seized, means for seizing said trunk line over one of said paths, and means controlled by such seizure for rendering one of said groups inaccessible to the 40 said set of wipers of said first-mentioned switch.

45. 39. In a telephone system, the combination 45 with an automatic switch, a trunk line terminating in said switch, trunk lines divided into groups and sub-groups commonly accessible to a set of wipers cooperative with the said groups and sub-groups, of a plurality of paths over which the first-mentioned trunk line may be seized, means for seizing said trunk line over one of said paths, and means controlled by such seizure for rendering one of said groups inaccessible to the 55 said set of wipers of said first-mentioned switch.

40. In a telephone system, the combination 60 with an automatic switch, a trunk line terminating in said switch, trunk lines divided into groups commonly accessible to a set of wipers cooperative with the said groups, means for seizing said trunk line, and means operative upon such seizure for applying an electrical potential to a conductor

of said trunk line, and means operative responsive to said potential for preselecting one of said groups.

41. In a telephone system, the combination 70 with an automatic switch, a trunk line terminating in said switch, trunk lines divided into groups commonly accessible to a set of wipers cooperative with the said groups, means for seizing said trunk line, of means operative upon such seizure for applying an electrical potential to a conductor of said trunk line, and means operative responsive to said potential for rendering one of said groups inaccessible to said switch.

42. In a telephone system, the combination 80 with an automatic switch, a trunk line terminating in said switch, trunk lines divided into groups commonly accessible to a set of wipers of the switch cooperative with the said groups, of a relay in the said switch 85 for selecting a particular one of said groups, two paths over which the first-mentioned trunk line may be seized, means for seizing said trunk line over either said paths, and means operative for energizing said relay 90 when said switch is seized over a particular one of said paths.

43. In a telephone system, a calling line, a reciprocal operating switch which will operate alternatively as an impulse repeater 95 and as a selector, a selector, a trunk line having said switch at one end and said selector at the other, a called line, means controlled from the calling line to seize said switch to thereby extend the connection over 100 the trunk to the selector, means for adapting the said switch to operate as a trunk impulse repeater consequent to its said seizure, and means on the calling line for operating the repeater for directly controlling the 105 selector to extend the connection in the direction of the called line.

44. In a telephone system, a calling line, a reciprocal operating switch which will operate alternatively as an impulse repeater 110 and as a selector, but normally operating as a trunk terminating selector, a selector, a trunk line having said switch at one end and said selector at the other, a called line, means controlled from the calling line to seize said 115 switch and to thereby extend the connection over the trunk to the selector, means for adapting the said switch to operate as a trunk impulse repeater consequent to its said seizure, and means on the calling line for directly controlling said repeater and the selector to extend the connection in the direction of the called line.

45. In a telephone system, a trunk line, 125 calling and called lines, a reciprocal operating switch at one end of the trunk which is operative as a trunk impulse repeater for traffic outgoing over the trunk and as a selector for traffic incoming over the trunk, a selector switch at the other end of the trunk 130

controlled over the trunk, means controlled from a calling line for extending a connection from the last said calling line through the reciprocal operating switch operating as 5 an impulse repeater and over the trunk in an outgoing direction to the selector toward a said called line, means controlled from another calling line for extending a connection over the trunk in an incoming direction to 10 the said switch, and means for then operating last said switch from the last said calling line to extend the call toward another said called line.

46. In a telephone system, calling and 15 called lines, a trunk, a reciprocal operating switch at one end of the trunk which is operative as a trunk impulse repeater for traffic outgoing over the trunk and alternatively as a selective switch for traffic incoming over 20 the trunk, an automatic switch for extending outgoing connections in the direction of a called line at the other end of the trunk, an impulse repeater mechanism interlinked with the automatic switch at said other end 25 of the trunk operative for traffic incoming over the trunk to the reciprocal operating switch at said one end thereof, means operated from a said calling line for seizing the said repeater mechanism to extend said calling line over the trunk in an incoming direction toward a said called line at said one end of the trunk, means for then directly operating the said reciprocal operating switch as a selective switch over the trunk from last 30 35 40 45 50 said calling line to further extend said calling line toward said called line, means operated from another said calling line at said one end of the trunk for seizing said reciprocal operating switch to extend last said calling line over the trunk in an outgoing direction to said automatic switch, means in said reciprocal operating switch for converting it into a trunk impulse repeater responsive to last said seizure, and means including the converted said repeater operated over last said calling line and the trunk for then directly operating the said automatic switch to further extend last said calling line in an outgoing direction toward another said called line.

47. In a telephone system, a calling line, called lines, a trunk, a reciprocal operating switch at one end of the trunk which is operative as a trunk impulse repeater for traffic outgoing over the trunk and alternatively as a selective switch for traffic incoming over the trunk, an automatic switch for extending outgoing connections from the other end of the trunk, an impulse repeater mechanism 55 60 65 interlinked with the automatic switch at the other end of the trunk operative for traffic outgoing over the trunk to the reciprocal operating switch at the said one end thereof, two groups of switches having access to specific called said lines, said switches selective-

ly seizable by the reciprocal operating switch when operating as a selective switch, means controlled from the calling line for directly seizing the said repeater mechanism differently, means in the reciprocal operating 70 switch for adapting it through introducing a set-up condition therein depending upon in which manner the said repeater mechanism is seized for operating as a selective switch for seizing switches in only one or 75 only the other of the said two groups of switches, and means on the calling line for directly operating the last said switch seized to extend the calling line to the desired said called line. 80

48. In a telephone system, a common mechanism at one end of a two-way trunk which will operate as an impulse repeater if the trunk is seized at the end having the said mechanism and which will operate as a 85 directly controlled movable connective switch if the trunk is seized at the opposite end thereof.

49. In a telephone system, a trunk terminating common mechanism in a two-way 90 trunk which will operate as an impulse repeater or as a selector depending upon which end of the trunk is seized.

50. In a telephone system, a common linking mechanism at a near end of a two-way 95 switching trunk which will operate as impulse repeater or as a selective switch depending upon if the trunk is seized from the near end or from the far end, respectively.

51. In a telephone system, a common linking mechanism at one end of a two-way switching trunk which will operate as an impulse repeater if the trunk is seized at the end having the said mechanism and which will operate as a selector if the trunk is seized 105 at the opposite end thereof.

52. In a telephone system, a line switch which will automatically operate to hunt for a disengaged line accessible thereto, talking circuits in the line switch, and automatically 110 applied means for applying a tone to the talking circuits of the switch for the period the said switch is hunting.

53. In a telephone system, a line switch terminating a calling line, means on the calling line to initiate the automatic hunting of the line switch seeking an idle leading-out line to seize, and automatically applied means for applying a tone audible along the calling line only during the period the line 115 switch is hunting.

54. In a telephone system, a calling line, a terminating hunting switch therefor, other lines accessible from the switch for successive test as to their respective busy or idle 120 state, a tone source, means on the calling line for initiating the hunting operation of the said hunting switch and for seizing the first idle line tested, and automatically applied means for applying the tone source to the 130

- calling line only during the time the hunting switch is hunting.
55. In a telephone system, the combination with two groups of trunk lines, means for making trunk lines in either group busy, of a trunk line terminating in two non-numerical switches, means for seizing the last-mentioned trunk line, and means operative responsive to said seizure for operating one of 10 said switches to search for an idle trunk line in one of said groups, and means operative after a predetermined interval for causing said other switch to search for an idle trunk line in the other of said groups.
56. In a telephone system, the combination with two groups of trunk lines, of a trunk line terminating in two non-numerical switches, said switches having access to said two groups of trunk lines, means for making some of said other trunk lines busy, and means controlled by the busy or idle condition of certain of said other trunk lines for determining which one of said switches shall be operated.
57. In a telephone system, the combination with two groups of trunk lines, means for making trunk lines in either group busy, of a trunk line terminating in a two-element switch, automatic means for maintaining one 30 of said switches in association with an idle trunk line, means for seizing said trunk line, and means for causing the other of said switches to search for an idle trunk line responsive to such seizure.
58. In a telephone system, the combination with a trunk line terminating in a non-numerical switch, other trunk lines accessible thereto, automatic means for causing said switch to maintain itself associated with an 40 idle one of said trunk lines, and means for placing a busy guard on the first-mentioned trunk line during the operation of the said automatic means.
59. In a telephone system, the combination with a group of trunk lines, means for making some of said trunk lines busy, of a trunk line terminating in an automatic switch, bank contacts accessible to said switch to which said trunk lines are connected, 50 means for causing said switch to operate to maintain said wipers in association with an idle one of said trunk lines, and means for busying the first-mentioned trunk line while said switch is operating.
60. In a telephone system, the combination with a non-numerical switch, a trunk line terminating in two sets of wipers for said switch, trunk lines accessible to each set of wipers, means for making some of said 60 trunk lines busy, and automatic means for maintaining one of said sets of wipers always associated with an idle one of said trunk lines.
61. In a telephone system, the combination with a trunk line terminating in a non- 65 numerical switch, two sets of wipers for said switch, trunk lines accessible to each set of wipers, means for seizing said trunk line, and means for operating both of said wiper sets to search for an idle one of said trunk lines.
62. In a telephone system, the combination with a trunk line terminating in a non-numerical switch, two sets of wipers for said switch, trunk lines accessible to each set of wipers, means for seizing said trunk lines, means for operating both of said wiper sets to search for an idle one of said trunk lines, and means operative when one of said sets engages an idle trunk line for stopping the 70 operation of both of said sets.
63. In a telephone system, the combination with a trunk line terminating in a non-numerical switch, means for seizing said trunk line, trunk lines accessible to said switch, means responsive to the seizure of the first-mentioned trunk line for operating said switch to search for an idle one of said trunk lines, and means operative, if all the said 75 trunk lines are busy, for stopping the searching operation of said switch.
64. In a telephone system, the combination with a trunk line terminating in a non-numerical switch, means for seizing said trunk line from a subscriber's line, trunk lines accessible to said switch, means responsive to the seizure of the first-mentioned trunk line for operating said switch to search for an idle one of said trunk lines, means operative if all of said trunk lines are busy for stopping the searching operation of said switch, and means for giving a busy tone to said calling subscriber's line and for applying a busy tone to said first-mentioned trunk line.
65. In a telephone system, the combination with a trunk line terminating in a lineswitch, bank contacts and wipers for said switch, trunk lines terminating in said bank contacts, a set of normally busy bank contacts for said switch, means for making said trunk lines busy, means for seizing said switch, and means operative if all said trunk lines are busy for moving said busy potential from 90 normally busy bank contacts.
66. In a telephone system, the combination with a trunk line terminating in a non-numerical switch, two sets of wipers for said switch, trunk lines accessible to each set of wipers, means for seizing said trunk lines, means for operating both of said wiper sets to search for an idle one of said trunk lines at the same time, and means operative responsive to either one of said wiper sets seizing an idle trunk line for stopping the searching operation of the other of said 100 wiper sets.
67. In a telephone system, trunk lines, a calling line, a plurality of switches terminating the calling line having access to the trunk lines, means controlled over the call- 105
- 110
- 115
- 120
- 125
- 130

ing line for initiating the simultaneous operation of the switches to search for an idle one of said trunk lines, means for making certain of said trunk lines busy, and means controlled by the busy or idle condition of certain of said trunk lines for determining if only one of said switches shall operate responsive to said control.

68. In a telephone system, a trunk line, a switch terminating the trunk line, wipers of the switch, trunk lines accessible from said wipers, means for seizing the trunk line, means responsive to only seizing said trunk line for causing the operation of said wipers

10 15 to search for an idle one of said trunk lines, and means responsive to all the trunk lines being busy for stopping the searching operation of the wipers without an idle one of said trunk lines being found by the wipers.

20 69. In a telephone system, a calling line, a non-numerical automatic switch terminating the conductors of the calling line, other lines accessible from the switch, means in the switch for testing the busy and idle condition of the individual said other lines, means associated with the individual said other lines for barring connection by the switch to the individual said other lines responsive to a busy condition of the respective said other lines, means for initiating the testing operation by the switch responsive to only closing a circuit including a conductor of the calling line, and means for applying a busy condition to a said conductor of the calling line responsive to all the said other lines being busy without testing all the individual said other lines.

70. In a telephone system, a calling line, a group of other lines, an automatic switch terminating the calling line, means for initiating a call over the calling line by only closing a circuit path including a conductor of the calling line for causing the switch to search for and seize an idle one of the said other lines, means for barring the seizure of the individual said other lines when busy, and means for applying a busy to the calling line indicative that all the said other lines are busy without the switch individually testing all the said other lines.

40 45 50 55 60 65 71. In a telephone system, a calling line, a group of other lines, an automatic switch terminating the calling line, means for initiating a call over the calling line by only closing a circuit path including a conductor of the calling line for causing the switch to search for and seize an idle one of the said other lines, means for barring the seizure of the individual said other lines when busy, a chained circuit path closed only when all of said other lines are busy, and means controlled by the closure of said chain circuit path for applying a busy to the calling line to manifest that all the said other lines are

busy without the switch individually testing all the said other lines.

72. In a telephone system, a calling line, a group of other lines, an automatic switch terminating the calling line, means for initiating a call over the calling line by only closing a circuit path including a conductor of the calling line for causing the switch to search for and seize an idle one of the said other lines, means for barring the seizure of the individual said other lines when busy, a relay operated only when a predetermined number of said other lines are busy, and means controlled by said relay when operated for applying a busy to the calling line to manifest that the predetermined number of said other lines are busy without the switch individually testing all the said other lines.

73. In a telephone system, a calling line, a group of other lines, an automatic switch terminating the calling line, means directly controlled over the calling line for causing the switch to search for and seize an idle one of the said other lines, means for barring the seizure of the individual said other lines when busy, a relay operated only when a predetermined number of said other lines are busy, and means controlled by said relay when operated for applying a busy to the calling line to manifest that the predetermined number of said other lines are busy without the switch individually testing all the said other lines.

74. In a telephone system, a calling line, a group of other lines, an automatic switch terminating the calling line, means directly controlled over the calling line for causing the switch to search for and seize an idle one of the said other lines, means for barring the seizure of the individual said other lines when busy, a relay only operated responsive to a predetermined number of said other lines becoming busy, and means controlled by said relay when operated for applying a busy to the calling line indicative that the switch cannot extend a connection to any of said other lines.

75. In a telephone system, a calling line, an automatic switch terminating the calling line, other lines accessible from said switch, means including a test terminal individual to the respective other lines for barring the respective other lines from seizure by the switch only if the respective other lines are made busy, means for causing the switch to search over the other lines for an idle one thereof responsive to initiating a call over the calling line by only closing a circuit path including a conductor of the calling line, and means responsive to the searching operation only in case all the other lines are busy for causing a tone to be applied audible on the calling line.

76. In a telephone system, a calling line, an automatic switch terminating the calling

70

75

120

125

130

line, other lines accessible from said switch, means including a test terminal individual to the respective other lines for barring the respective other lines from seizure by the switch only if the respective other lines are made busy, means for causing the switch to search over the other lines for an idle one responsive to directive control over the calling line, and means responsive to the searching operation only in case a predetermined number of the other lines are busy for causing a tone to be applied audible on the calling line.

77. In a telephone system, a calling line, a switch having two sets of wipers terminating the calling line, other lines accessible from the respective said wiper sets, means directly controlled over the calling line for initiating the operation of only one of said sets of wipers by only closing a circuit path including a conductor of the calling line to select an idle one of said other lines, and means operated only after the first said operation has been initiated for then initiating the operation of the other of said sets of wipers to select an idle one of said other lines.

78. In a telephone system, a calling line, a pair of automatic switches terminating the calling line, a set of wipers individual to each said switch, other lines accessible from the said wiper sets, automatic means for initiating the operation of only one of said wiper sets to search for an idle one of said other lines, and automatic means operated only after first said operation has been initiated for then initiating the operation of the other of said wiper sets to search for an idle one of said other lines.

79. In a telephone system, a calling line, a pair of automatic switches terminating the calling line, a set of wipers individual to each said switch, a specific group of other lines accessible from the respective wiper sets, automatic means for initiating the operation of only one of the wiper sets to search for an idle one of said other lines only of its corresponding group, and automatic means operated only after first said operation has been initiated for then initiating the operation of the other of said wiper sets to search for an idle one of said other lines only of its corresponding group.

80. In a telephone system, a calling line, a pair of automatic non-numerical switches terminating the calling line, a set of wipers individual to each said switch, a specific group of other lines accessible from the respective wiper sets, automatic means operated over the calling line for initiating the operation of only one of the said wiper sets to search for an idle one of the lines of its corresponding group, and automatic means operated only after first said operation has been initiated and progressed for then initiating the operation of the other wiper set for

reaching for an idle line in its corresponding group.

81. In a telephone system, a trunk line having two branches at the incoming end, an automatic switch in which said trunk terminates at the outgoing end, two groups of lines accessible to said switch corresponding, respectively, to said two branches, automatic switching mechanism for extending a call to the trunk via either of said branches, means for then operating said switch to further extend the call by way of an idle one of said lines, and discriminating means for causing said switch to select an idle line in the particular group which corresponds to the incoming branch in use.

82. In a telephone system, a trunk line having two branches at the incoming end, an automatic switch in which said trunk terminates at the outgoing end, two groups of lines accessible to said switch corresponding, respectively, to said two branches, automatic mechanism for extending a call to the trunk via either of said branches, means for then operating said switch to further extend the call by way of an idle one of said lines, testing means in said switch, and means associated with said incoming branches for controlling the action of said testing means to cause the said switch to select an idle line in the particular group which corresponds to the incoming branch in use.

83. In a telephone system, a trunk line having two branches at the incoming end, an automatic switch in which said trunk terminates at the outgoing end, two groups of lines accessible to said switch corresponding, respectively, to said two branches, automatic switching mechanism for extending a call to the trunk via either of said branches, means for then operating said switch to further extend the call by way of an idle one of said lines, testing means in said switch normally effective to cause said switch to select an idle line in a particular one of said groups corresponding to a particular incoming branch, and means responsive in case the call is received over the other incoming branch for causing said switch to select an idle line in the other group.

84. In a telephone system, a trunk line having two branches at the incoming end, an automatic switch in which said trunk terminates at the outgoing end, two groups of lines accessible to said switch corresponding, respectively, to said two branches, automatic switching mechanism for extending a call to the trunk via either of said branches, means for then operating said switch to further extend the call by way of an idle one of said lines, testing means in said switch for causing the selection of an idle line in a particular one of said groups, other testing means in said switch for causing the selection of an idle line in the other group, and means for

automatically rendering effective only the testing means which is associated with the group corresponding to the incoming branch in use.

85. In a trunking system, incoming trunks, a smaller number of outgoing trunks, switching means associated with each incoming trunk and responsive to the seizing thereof for hunting for and connecting the seized incoming trunk with an idle outgoing trunk, means for transmitting a busy signal to any incoming trunk when seized responsive when all of said outgoing trunks are engaged by other incoming trunks, means for discontinuing the busy signal to said seized incoming trunk if any of the outgoing trunks become idle while said incoming trunk is still seized and means for continuing the trunk hunting movement of the corresponding switching means of said seized incoming trunk after the busy signal is discontinued and until the idle outgoing trunk is found.
86. In a telephone system, a leading-in line, a pair of non-numerical switches terminating the leading-in line, a specific group of trunk lines accessible from the respective said switches, means for making certain of the said trunk lines of the group busy, means for initiating a call on the leading-in line, automatic means responsive to the initiation of the call for causing one of said switches to selectively hunt in an automatic testing operation over busy trunk lines of its said group and seize the first idle trunk line tested, and automatic means involved in last said means for causing the other of said switches to selectively hunt in an automatic testing operation over busy trunk lines of its said group and seize the first idle trunk line tested.
87. In a telephone system, a leading-in line, a pair of non-numerical switches terminating the said line, a group of lines accessible from said switches respectively, one of said switches being automatically pre-selecting and the other of said switches being automatically post-selecting with respect to idle lines of its said group of lines, means for making certain of said lines in the respective groups busy, means for initiating a call on the leading-in line, means responsive to the initiation of a call on the leading-in line for causing said other switch to selectively hunt in an automatic testing operation over busy ones of its accessible lines and seize the first idle line tested, and means responsive to said other switch hunting for a predetermined period of time for causing said one switch to thereupon seize its pre-selected idle line.
88. In a telephone system, a leading-in line, a pair of non-numerical switches terminating the said line, a group of lines accessible from said switches, one of said switches being automatically pre-selecting and the other of said switches being automatically post-selecting with respect to idle lines of said group of lines.

lines, means for making certain of said lines in the group busy, means for initiating a call on the leading-in line, means responsive to the initiation of a call on the leading-in line for causing said other switch to selectively hunt in an automatic testing operation over busy ones of accessible lines and seize the first idle line tested, and means responsive to said other switch hunting over a predetermined number of busy lines for causing said one switch to thereupon seize its pre-selected idle line.

89. In a telephone system, a leading-in line, a pair of non-numerical switches terminating the said line, a group of lines accessible from said switches respectively, one of said switches being automatically pre-selecting and the other of said switches being automatically post-selecting with respect to idle lines of its said group of lines, means for making certain of said lines in the respective groups busy, means for initiating a call on the leading-in line, means responsive to the initiation of a call on the leading-in line for causing said other switch to selectively hunt in an automatic testing operation over busy ones of its accessible lines and seize the first idle line tested, and means responsive to said other switch hunting for a predetermined period of time for causing said one switch to thereupon seize its pre-selected idle line.

90. In a telephone system, a leading-in line, a pair of non-numerical switches terminating the said line, a group of lines accessible from said switches, one of said switches being automatically pre-selecting and the other of said switches being automatically post-selecting with respect to idle lines of said group of lines, means for making certain of said lines in the group busy, means for initiating a call on the leading-in line, means responsive to the initiation of a call on the leading-in line for causing said other switch to selectively hunt in an automatic testing operation over busy ones of its accessible lines and seize the first idle line tested, and means responsive to said other switch hunting for a predetermined period of time for causing said one switch to thereupon seize its pre-selected idle line.

91. In a telephone system, a leading-in line, trunk lines, switching mechanism comprising two interlinked independently operated elements for extending connection from the leading-in line to an idle one of said trunk lines, means which will automatically operate to cause one of the said elements to maintain a pre-selection of an idle trunk and to automatically operate to re-pre-select an idle trunk responsive to a pre-selected trunk becoming busy while the said leading-in line is idle, means for initiating a call on the leading-in line to thereby initiate the operation of the switching mechanism wherein the other of said elements will start hunting for an idle trunk line to seize,

and means operated at the expiration of a period of hunting by said other element which will cause the said one element to seize the pre-selected trunk.

5 92. In a telephone system, a leading-in line, trunk lines, switching mechanism comprising two interlinked independently operated elements for extending connection from the leading-in line to an idle one of said 10 trunk lines, means which will automatically operate to cause one of the said elements to maintain a pre-selection of an idle trunk and to automatically operate to re-select an idle trunk responsive to a pre-selected trunk 15 becoming busy while the said leading-in line is idle, means for initiating a call on the leading-in line to thereby initiate the operation of the switching mechanism wherein the other of said elements will start hunting for 20 an idle trunk line to seize, means operated at the expiration of a period of hunting by said other element which will cause the said one element to seize the pre-selected trunk, and further means operated by one of said 25 elements to disable the other of said elements responsive to an element seizing an idle trunk.

93. In a telephone system, a leading-in line, trunk lines, switching mechanism comprising two interlinked independently operated elements for extending connection from the leading-in line to an idle one of said trunk lines, means controlled over the leading-in line to initiate the operation of the switching mechanism wherein one of the elements will start hunting for an idle trunk line to seize, means operated at the expiration of a predetermined period of hunting by the said one element wherein the other element will thereupon start hunting for an idle trunk line to seize coincident with the said one element, and means for disabling the switching mechanism against hunting responsive to all of the trunks becoming busy.

45 94. In a telephone system, a leading-in line, trunk lines, switching mechanism comprising two interlinked independently operated elements for extending connection from the leading-in line to an idle one of said 50 trunk lines, means controlled over the leading-in line to initiate the operation of the switching mechanism wherein one of the elements will start hunting for an idle trunk line to seize, means operated at the expiration of a predetermined period of hunting by the said one element wherein the other element will thereupon start hunting for an idle trunk line to seize coincident with the said one element, a tone source, and means 55 for disabling the switching mechanism against hunting and for applying the tone source to the leading-in line responsive to all of the trunk lines being busy.

95. In a telephone system, a first automatic switch, an idle leading-in line accessible from

the switch, an automatic selective switch terminating the leading-in line, a group of idle lines accessible from the selective switch, automatic means for barring the individual said lines when busy against seizure by the 70 selective switch, automatic means for barring the leading-in line when busy against seizure by said first switch, and automatic means for barring said idle leading-in line against seizure by said first switch responsive to a busy line condition in said group of lines.

96. In a telephone system, a first automatic switch, an idle leading-in line accessible from the switch, a non-numerical switch terminating the leading-in line, a group of idle lines accessible from the non-numerical switch, automatic means for causing the non-numerical switch to seize an idle said accessible line responsive to said first switch seizing the leading-in line, automatic means for barring the individual said lines when busy against seizure by the non-numerical switch, means for barring the leading-in line when busy 80 against seizure by the said first switch, and automatic means for barring said idle leading-in line against seizure by said first switch responsive to a busy line condition in said group of lines.

97. In a telephone system, a first automatic switch, an idle leading-in line accessible from the switch, a non-numerical switch terminating the leading-in line, a line accessible from the non-numerical switch, automatic means for causing the non-numerical switch to seize the said accessible line responsive to said first switch seizing the leading-in line, automatic means for barring said accessible line when 90 busy against seizure by the non-numerical switch, means for barring the leading-in line when busy against seizure by the said first switch, and automatic means for barring said idle leading-in line against seizure by said first switch responsive to said accessible line 95 becoming busy.

98. In a telephone system, a first automatic switch, an idle leading-in line accessible from the switch, a non-numerical switch terminating the leading-in line, a group of idle lines accessible from the non-numerical switch, automatic means for causing the non-numerical switch to seize an idle said accessible line responsive to said first switch seizing the leading-in line, automatic means for barring the individual said lines when busy against seizure by the non-numerical switch, means for barring the leading-in line when busy 100 against seizure by the said first switch, and automatic means for barring said idle leading-in line against seizure by said first switch responsive to said accessible line 105 becoming busy.

99. In a telephone system, a first automatic switch, an idle leading-in line accessible from the switch, a non-numerical switch terminat-

- ing the leading-in line, means for operating the switch only in a progressive advance movement, a group of idle lines accessible from the non-numerical switch, automatic 5 means for causing the non-numerical switch to seize an idle said accessible line responsive to said first switch seizing the leading-in line, automatic means for barring the individual said lines when busy against seizure 10 by the non-numerical switch, means for barring the leading-in line when busy against seizure by the said first switch, and automatic means for barring said idle leading-in line against seizure by said first switch responsive to a predetermined number of lines 15 of said group of lines becoming busy.
100. In a telephone system, a first automatic switch, an idle leading-in line accessible from the switch, a non-numerical 20 switch terminating the leading-in line, means for operating the switch only in a progressive advance movement, a group of idle lines accessible from the non-numerical switch, automatic means for causing the non- 25 numerical switch to seize an idle said accessible line responsive to said first switch seizing the leading-in line, automatic means for barring the individual said lines when busy against seizure by the non-numerical switch, 30 means for barring the leading-in line when busy against seizure by the said first switch, and automatic means for barring said idle leading-in line against seizure by said first switch responsive to certain of said lines of 35 said group of lines becoming busy.
101. In a telephone system, a trunk line, a plurality of trunk hunting switches terminating said trunk line, each switch having access to a different group of trunk lines, and 40 means responsive to a call received over said trunk line for operating one or more of said hunting switches to extend the call, the number of switches operated depending on the busy or idle condition of the trunk lines 45 accessible to said switches.
102. A switching device comprising two permanently paired rotary line switches for use alternatively in extending connections from a calling line to called lines, and means 50 included in said device for testing the called lines.
103. A rotary line switch, trunk lines accessible from said switch, means for making certain of said lines busy, means for 55 causing the line switch to seize an idle said trunk line responsive to initiating a call on the leading-in line of said switch, automatic means for keeping the switch in pre-selective relation with an idle one of said trunk lines 60 in readiness for seizing said pre-selected trunk line responsive to a call being initiated on the leading-in line, and means for preventing a call from being initiated on the leading-in line while the switch is in the act 65 of pre-selecting an idle line.

104. In a telephone system, a trunk line for handling traffic destined thereover in either direction, switch mechanism for seizing the trunk line at a random one of the ends thereof, automatic switch mechanism 70 for extending connections away from the end of the trunk line distant from the end seized, an operating electro-magnetic device for each said switch mechanism, means for sending electric impulses over the trunk line from the end seized to operate the electro-magnetic device at said distant end thereof to cause the corresponding automatic switch mechanism to thereby extend connection away from the trunk line, a relay individual to the trunk line, and means whereby said relay will repeat impulses sent over the trunk line from the seized end thereof for operating the electro-magnetic device at the corresponding 75 distant end of the trunk line regardless of the direction of traffic destination. 80
105. In a telephone system, a trunk line having not to exceed two conductors for handling traffic thereover in either direction, switch mechanism for seizing the trunk line 90 at a random one of the ends thereof, automatic switch mechanism for extending connections away from the end of the trunk line distant from the end seized, an operating electro-magnetic device for each said switch mechanism, means for sending electric impulses over the trunk line from the end seized to operate the electro-magnetic device at said distant end thereof to cause the corresponding automatic switch mechanism to 95 thereby extend connection away from the trunk line, a relay individual to the trunk line, and means whereby said relay will repeat impulses sent over the trunk line from the seized end thereof for operating the electro-magnetic device at the corresponding distant end of the trunk line regardless of the direction of traffic destination. 100
106. In an automatic telephone system, a trunk line terminating in a pre-selector and a post-selector, groups of lines accessible from said selectors, means for seizing said trunk line, means operated responsive to said seizure for causing the post-selector to hunt for an idle accessible line and seize the same 110 to extend the trunk line thereto, and means for causing the pre-selector to seize the pre-selected line to extend the trunk line thereto, the latter said seizure occurring only in the event that the post-selector has made a 115 predetermined hunting operation and failed to find an idle line. 120
107. In an automatic telephone system, a trunk line terminating in a pre-selector and a post selector, groups of lines accessible from said selectors, means for seizing said trunk line, means operated responsive to said seizure for causing the post-selector to hunt for an idle accessible line and seize the same 125 to extend the trunk line thereto, means for 130

- causing the pre-selector to seize the preselected line to extend the trunk line thereto, the latter said seizure occurring only in the event that the post-selector has made a predetermined hunting operation and failed to find an idle line, and means for causing the pre-selector to make a hunting operation before seizing in the event the preselected line becomes busy while the post-selector is hunting.
108. In an automatic telephone system, a trunk line terminating in selective switches, lines accessible from the respective switches, means for seizing the trunk line, and means governed by the condition of the lines for determining which of said switches will extend the connection from the trunk line to one of said lines, responsive to the seizure of the trunk line.
109. In an automatic telephone system, a switch mechanism constituting a plurality of sets of wipers, a group of line terminals in sets for the respective sets of wipers, automatic means for selectively operating said sets of wipers, a trunk line individual to the sets of wipers in common and companion thereto, and means depending upon the electrical potential existing upon certain of the terminals of said groups of terminals for determining which one of said sets of wipers will seize a specific set of line terminals, to thereby identify a group and a particular set of line terminals of the latter said group.
110. In an automatic telephone system, a selective switch mechanism, a group of lines accessible from said mechanism, a leading-in line of said switch mechanism, means for applying control over the leading-in line to thereby cause the switch mechanism to hunt for and seize the first encountered idle line of the group to thereby connect the leading-in line with the said idle line, and means whereby the switch mechanism will be disabled from hunting responsive to all the lines of the group becoming busy.
111. In an automatic telephone system, a selective switch mechanism, a group of lines accessible from said mechanism, a leading-in line of said switch mechanism, means for applying control over the leading-in line to thereby cause the switch mechanism to hunt for and seize the first encountered idle line of the group to thereby connect the leading-in line with the said idle line, and means whereby the switch mechanism will be disabled from hunting responsive to all the lines of the group becoming busy, regardless of the fact that said control may not have been applied over the leading-in line.
112. In an automatic telephone system, a selective switch mechanism having a plurality of sets of wipers, each said set having a talking wiper and a private wiper, a test relay specific to each said private wiper, a group of lines specific to each set of wipers, the terminals of which are subject to being swept by the corresponding wipers, automatic interrupter means in the switch mechanism for causing the test wipers to simultaneously sweep in hunting operation with respect to the corresponding line groups, and interlocking means between the test relays so arranged that in the event one of the test relays operates responsive to its corresponding test wiper finding an idle trunk, the latter said operation will disable the other of said relays from operating.
113. In an automatic telephone system, a selective switch mechanism having a plurality of sets of wipers, each said set having a talking wiper and a private wiper, a test relay specific to each said private wiper, a group of lines specific to each set of wipers, the terminals of which are subject to being swept by the corresponding wipers, a leading-in line to the switch mechanism, automatic means for causing the test wipers to simultaneously sweep in hunting operation with respect to the corresponding line groups, interlinking means between the test relays so arranged that in the event one of the test relays operates responsive to its corresponding test wiper finding an idle trunk, the latter said operation will disable the other of said relays from operating, and means controlled by the winding of the respective test relays for connecting the leading-in line through the talking wiper of the corresponding wiper set to the specific trunk the latter said wiper is sweeping when the corresponding said relay operates.
114. In a trunk system comprising a large number of line terminals, corresponding switches and a comparatively smaller number of trunks accessible thereby, means for establishing a busy condition for such line terminals as are not used in the connections responsive to the engagement of all of said trunks, and means for connecting said busy condition means to the line corresponding to any idle line terminal responsive to its being seized while all trunks are engaged.
115. In a straightforward trunking system, groups of incoming trunks, an individual switch for each trunk, a single group of trunks outgoing from said switches, smaller in number than the total number of incoming trunks and switches, means associated with each incoming trunk and its switch responsive to the seizing of the trunk for operating said switch to hunt for an idle outgoing trunk, means responsive when all outgoing trunks are engaged for establishing a busy condition for all the incoming trunks not in use, and means individual to each incoming trunk each responsive to the seizing of the corresponding trunk after the busy condition has been established for indicating at the terminals of said seized trunk such busy condition.
116. In a trunking system, groups of in-

coming trunks, switches each associated with an incoming trunk, a smaller number of trunks available to said switches, means associated with each incoming trunk for operating the corresponding switch to hunt for and connect said incoming trunk with an idle outgoing trunk, and means for transmitting a busy signal over the incoming trunk the corresponding switch of which is hunting for an idle outgoing trunk if all the outgoing trunks are engaged.

117. In a trunking system, groups of incoming trunks, switches one for each incoming trunk, a smaller number of trunks available to said switches and outgoing therefrom, means associated with each incoming trunk for operating the corresponding switch to hunt for and connect said incoming trunk with an idle outgoing trunk, means for transmitting a busy signal over the incoming trunk the corresponding switch of which is hunting for an idle outgoing trunk if all the outgoing trunks are engaged, and means for discontinuing the transmission of the busy signal over said incoming trunk if any one of said outgoing engaged trunks become idle during the trunk hunting movement of the corresponding switch.

118. In a trunking system, a two-way impulse path over a trunk wherein impulses passing in both directions over the trunk are repeated by the same relay.

119. In a trunking system, a two-way impulse path over a trunk wherein impulses passing in both directions over the trunk are received by the same winding of a relay and repeated.

In witness whereof, I hereunto subscribe my name this 21st day of June, A. D. 1921.
